WRITING MACHINE

William E. McFarland, Nutley, N. J., assignor to
 L. C. Smith & Corona Typewriters, Inc.,
 Syracuse, N. Y., a corporation of New York

Application September 30, 1937, Serial No. 166,527

80 Claims. (Cl. 197—153)

This invention relates to novel mechanism which may be employed to make typewritten copies; specifically the invention is directed to an improved writing machine or mechanism for making improved hectograph, photo-offset, or ordinary multiple copies and efficiently use the transfer material employed.

An object of my invention is to provide a writing machine for more efficiently producing typewritten copy.

Another object of my invention is to provide a compact and versatile writing machine adapted to be efficiently employed for normal and special typewriting purposes, such as manifolding, and hectograph and photographic master copy production.

Another object of my invention is to provide a writing machine whose carriage carried carbon ribbon is fed simultaneously in the direction of its width and length in uniform steps of feed to utilize the carbon transfer material in an easy and effective manner and to thereafter discard the used ribbon.

Another object of my invention is to provide improved master copies, free from smudging, tracking and dusting, for reproduction by hectograph, and photographic purposes.

Another object of my invention is to provide a writing machine having means for varying the size of angle which its ribbon makes with its writing line and maintaining the ribbon in a plurality of angular positions with respect to the writing line.

Another object of my invention is to provide a writing machine having means for disposing the ribbon in inoperative position below the writing line of the machine and maintaining the ribbon in this position so that the machine can be used for work outside the purposes of the ribbon, and the ribbon is located in an effective inoperative position.

Another object of my invention is to provide a writing machine having means operable incidental to carriage return for feeding a ribbon in substantially uniform steps simultaneously along the direction of its length and width to provide a substantially complete fresh transfer surface for each succeeding line of writing upon a single actuation of said means.

Another object of my invention is to provide a writing machine whose ribbon packs in snugly with a work sheet and platen.

Another object of my invention is to provide a preferred direction of oblique ribbon feed, and

ejecting the ribbon after a downward, and right to left feed.

Another object of my invention is to provide a front strike manifolding typewriter having a pack of individual ribbons fed as a unit and individual separators for moving the ribbons with respect to each other for paper interleaving.

Another object of my invention is to provide a front strike manifolding typewriter, having a pack of individual ribbons, a common guide structure for guiding the pack widthwise, and a common feed structure for feeding the ribbons as a unit, and individual ribbon separators for separating the ribbons from each other for paper interleaving.

Another object of my invention is to provide a writing machine with a pack of ribbons in a particular path cooperating with individual separating devices so the ribbons may be split thicknesswise with minimum strain on the ribbons and substantially without changing the path length of the individual ribbons during the splitting operation.

Another object of my invention is to spread the ribbons at the low end of the effective oblique stretch of a pack for paper interleaving.

Another object of my invention is to provide a writing machine having expedients whereby a common grip feed for a pack of ribbons may be employed to feed the ribbons from a multiple ply supply spool and whereby the longer outer plies from the spool are fed at an accelerated rate to overcome slack normally developing from the longer outer plies.

Another object of my invention is to provide a writing machine having a constantly effective tensioning device for a ribbon to impart retractive tension to said ribbon by meshable elements which slip relative to each other in a positive manner and at a predetermined point upon continuous ribbon feed.

Another object of my invention is to provide a writing machine having a plurality of carriage-carried devices separately and independently operable, one to line space a work sheet and the other to feed a ribbon, said devices being also collectively operable to simultaneously line space a work sheet and feed the ribbon.

Another object of my invention is to provide a writing machine having an improved grip feed roll assembly with a novel driving power connection to provide efficiently a wide range of uniform steps of ribbon feed.

Another object of my invention is to provide a writing machine having an automatically op-

erable bail lifter so that the paper bail pressure upon the work sheet is released during line spacing of the work sheet.

Other objects and advantages of my invention will be readily apparent from the following description:

Referring to the drawings,

Figure 1 is a top plan view of a typewriter embodying my invention showing the arrangement of the typewriter and the several assemblies added to the machine, and showing the swinging movement of the ribbon feeding lever which may be swung about its pivot free and clear of the line spacing lever of the typewriter.

Figure 2 is a front view of a portion of a typewriter embodying my invention, showing the oblique disposition of the effective stretch of ribbon in the writing line, and the oppositely tilted ribbon guiding and supporting assemblies at each end of the carriage.

Figure 3 is a view of the right hand end of a portion of a typewriter embodying my invention, and shows the location of the spool support and the ribbon guiding and tensioning apparatus at the upper end of the oblique stretch of the ribbon, and the adjusting means to regulate the effective operating position of the stretch of ribbon suspended along the platen.

Figure 4 is a view similar to Figure 3, but showing the position of the ribbon support, guide, and tension assembly when moved downward about its pivotal axis to dispose the effective stretch of ribbon below the field of type impacts and between the usual vibrating ribbon and the lower portion of the platen or paper holding rolls.

Figure 5 is a view of part of the left hand portion of a typewriter embodying my invention, showing the tilted mounting of the feed rolls and the arrangement of cooperating parts.

Figure 6 is a view of the ejector mechanism for the ribbons, and the ribbon separating elements, taken on line VI—VI of Figure 5, and illustrating the deflected ribbon path beyond the separating elements, and the relative ribbon paths when the ribbons are extended to sheet guiding position, and when the ribbons are operative adjacent the platen.

Figure 7 is a view taken on line VII—VII of Figure 5, in the direction of the arrows, illustrating a rear view of the feed roll device and the ribbon deflector plate for deflecting the ejected portion of the ribbons to the rear of the machine and under the platen shaft or axis.

Figure 8 is a view taken on line VIII—VIII of Figure 7, in the direction of the arrows, and illustrating a ratchet gear affixed to the main driving shaft of the driving feed roll, and a spring pressed pawl pivotally mounted on the rotatable driving drum.

Figure 9 is a cross sectional view of the pressure feed rolls and associated parts, taken on line IX—IX of Figure 6, showing the details of construction of the cooperating feed rolls and driving drum mechanism.

Figure 10 is a diagrammatic view showing the mounting and position of the ribbon separating assembly at the left end of the carriage and at the low end of the effective stretch of ribbon, the dotted lines representing the position of the slideable ribbon separators in outer or extended position.

Figure 11 is a perspective view of the ribbon separator and guide assembly used to guide and actuate the ribbons thicknesswise at the lower

end of the effective stretch of ribbon along the platen.

Figure 12 is a cross sectional view of the ribbon tension imparting unit, taken on line XII—XII of Figure 1, showing the details of construction of the spring driven constant tension device.

Figure 13 is a diagrammatic plan view of the cooperating meshing elements of the tension device, showing the relative position of the engaging teeth of the two meshing elements in normal 10 operating position as ribbon is being drawn from the spool.

Figure 14 is a diagrammatic plan view similar to Figure 13, but showing the relationship of the meshing elements after a definite degree of slack 15 in the ribbon has been taken up and retracted to the feed spool, such as slack developing from a rapid spin of the feed spool, or lost motion or slippage at any point along the stretch of ribbon 20 extending from the spool.

Figure 15 is a diagrammatic plan view similar to Figure 14, but showing the relationship of the meshing elements after a maximum amount of slack has been taken up and retracted to the supply spool, as in case of ribbon breakage, and 25 showing the stop element in operative position to limit further backward rotation of the supply spool and consequent unwinding of the spiral tension spring.

Figure 16 is a cross sectional view taken on line 30 XVI—XVI of Figure 1 of the ribbon supply spool and associated parts, showing the spool supported by pins to rotate concurrently with the large tension disc and showing details of the pivotal mounting of the supply spool platform assembly. 35

Figure 17 is a cross sectional view of the ribbon tension device, taken on line XVII—XVII of Figure 1, showing details of construction of the tension device, and cooperating parts to regulate and maintain the adjustment of the tensioning 40 spring.

Figure 18 is an enlarged top view of the tension device, the dotted lines showing the teeth of the small meshing or tensioning element and the spiral tension spring which cooperates to 45 maintain a counter feeding pressure on the large spool carrying disc.

Figure 19 is a sectional view taken on line 50 XIX—XIX of Figure 20, illustrating the mechanism for automatically lifting the paper bail during actuation of the line spacing lever.

Figure 20 is a view of the mechanism for automatically raising the paper bail during actuation of the line spacing lever, and showing details of the cam associated with the line space pawl carrier. 55

Figure 21 is a view of an assembly of carriage return levers, one comprising a ribbon feeding lever and the other comprising a line spacing lever, showing the manner in which the levers 60 are mounted to swing in non-colliding planes, and the free and independent pivotal mounting for each lever and the separate spring means for returning each lever independently to resting position after actuation.

Figure 22 is a diagrammatic view illustrating the manner in which the characters are impacted on the carbon strips, and showing how the lines of impacts on the carbon strips may be on new surface for each line written but closely compacted above the preceding impacts, and illustrating also the downward right to left direction of ribbon feed in combination with the upward line spacing of the work sheet. The dotted lines of Figure 22 illustrate the manner in which a 75

work sheet may be inserted in the typewriter cornerwise to facilitate the leading edge of the work sheet being interleaved with proper relation to the ribbon strips which may be moved directly 5 from operating position thicknesswise.

Figure 23 is a diagrammatic view illustrating an assembly of work sheets being fed around the platen preparatory to interleaving the assembly of sheets with the ribbons which are all shown as 10 in extended position in this view.

Figure 24 is a view similar to Figure 23, but illustrating the position of the assembly of work sheets after the innermost ply of ribbon has been actuated thicknesswise and snapped into position 15 against the first work sheet, after which the work sheets have been fed a sufficiently further distance to prepare for actuating the middle ply of ribbon.

Figure 25 is a view similar to Figures 23 and 24, 20 illustrating a further step in the interleaving of the ribbons with the work sheets, showing the position of the work sheets and ribbons after the middle ply of ribbon has been actuated thicknesswise and snapped into position against the 25 second work sheet after which the sheets have been fed a sufficiently further distance to prepare for actuating the outside ply of ribbon, and with the remaining extended ribbon ready to be snapped against the third sheet.

Figure 26 is a perspective view of the effective stretch of ribbon suspended along the platen in its down or inoperative position, and showing the entire effective stretch of ribbon below the writing line and slightly forward of the lower half of 35 the platen.

Figure 27 is a perspective view of the effective stretch of ribbon suspended along the platen in operative position, and adjusted at an operating angle to accommodate a maximum length line of writing, and illustrating the spiral or helical path 40 of the stretch of ribbon along the platen.

Figure 28 is a diagrammatic view taken on line XXVIII-XXVIII of Figure 27, showing the relationship of the strips of ribbon with respect to 45 the writing line at the lower end of the stretch of ribbon closely adjacent the low end guide means.

Figure 29 is a diagrammatic view similar to Figure 28, but taken on line XXIX-XXIX of 50 Figure 27, and showing the relationship of the strips of ribbon with the platen and with the writing line at the leftmost limit of the effective maximum writing line.

Figure 30 is a diagrammatic view taken on line 55 XXX-XXX of Figure 27, showing the relationship of the strips of ribbon with respect to the platen and the writing line at the center of the effective maximum writing line.

Figure 31 is a diagrammatic view taken on line 60 XXXI-XXXI of Figure 27 and showing the relationship of the strips of ribbon with respect to the platen and writing line at the rightmost limit of the effective maximum writing line.

Figure 32 is a diagrammatic view taken on line 65 XXXII-XXXII of Figure 27 and showing the relationship of the strips of ribbon with respect to the writing line at the upper end of the stretch of ribbon closely adjacent the ribbon guide roller.

Figure 33 is a cross sectional view taken on line 70 XXXIII-XXXIII of Figure 9 and illustrates the small area of contact between the larger driving roll and the outer ply of ribbon and the large area of contact between the inner 75 ply of ribbon and the smaller driven roll and

the dotted line shows position the driven roll may attain when it is desired to provide a space between the two rolls.

Figure 34 is a perspective view of the driven roll bracket, ribbon deflector and the spring actuator which tends to swing the bracket towards the driving roll to provide a pressure between the driving and driven rolls shown in Figure 9.

Figure 35 is a side elevation of the spring 10 shown in Figure 34.

Figure 36 is a sectional view taken on line XXXVI-XXXVI of Figure 21 in the direction of the arrows.

Although the invention as illustrated and hereinafter described, is shown in connection with a conventional front strike typewriter, it may, with some modifications of the specific parts shown, be effectively employed on other conventional front strike typewriters as well as on other types 15 of writing machines and on especially those having a traveling carriage. The construction and operation of conventional types of writing machines of today are so well known that the same shall not be described in detail here, and the one shown in the drawings shall be described 20 only to the extent that the invention may be readily ascertained by those skilled in the art of writing machines.

The known front strike typewriting machine 30 illustrated in the drawings in connection with the improvements of the present invention as embodied therein in a preferred form comprises a stationary frame 10 on which is mounted a longitudinally movable letter space carriage assembly 11. The carriage assembly includes a pair of oppositely disposed end plates 12 and 13 having a shaft 14 journaled therein. A cylindrical platen 15, which may be fairly hard, is carried by said shaft 14 and is located between said end plates 12 and 13. A paper release lever 16 is pivotally mounted on the end plate 13 and is mechanically connected (connection not shown) to the front paper holding rolls 17 and the rear paper holding rolls (not shown) so that upon actuation of lever 16, the paper holding 40 rolls may be moved towards or away from the platen 15. A pair of spaced arms 18 are pivoted on a tabulator rack 19 and carry a paper table 20 whose lower edge, when the paper table 50 is in operative position, terminates adjacent the rear longitudinal edge of a paper deflection plate 43 extending beneath the platen 15 to guide a work sheet during initial feeding of the same to the typewriter.

Adjacent the left hand end of the platen 15 55 is a line space ratchet gear 21 mounted on the shaft 14 so that actuation of the ratchet gear 21 causes actuation of shaft 14 and platen 15. Mounted for rotation on the shaft 14 is a plate 22 having a guard flange 23 covering a portion 60 of the periphery of the ratchet gear 21. A handle 24 is secured to plate 22 and extends above the platen 15. By actuating the handle 24 the position of the flange 23 may be varied to cover and uncover some of the teeth of the 65 ratchet gear 21. A line space pawl carrier 25 is pivotally mounted on shaft 14 and extends outwardly beyond the guard flange 23. A line space pawl 26 is pivoted to the outer end of the pawl carrier 25. A spring 27, at all times tending to 70 force the effective part of the pawl 26 towards the teeth of the ratchet gear 21, is secured to carrier 25 and to pawl 26. A link 28 is pivotally connected to the carrier 25 and to the outer end 75 of the short arm of a line space lever pivotally

mounted on a horizontal plate or shelf 29 integral with the end plate 12. A stop 30 is integral with the plate 29, and extends upwardly therefrom at the front edge thereof. Another stop 31 is secured to said plate 29 and is spaced from said stop 30. Said stops 30 and 31 limit the extent of movement of the line space lever upon full actuation thereof. Upon full actuation of the line space lever from left to right, the platen 15 may be rotated to feed a mounted work sheet 1, 2 or 3 spaces depending upon the position of the flange 23. A paper bail has side arms 32 pivotally mounted on a marginal spacer bar 33 and a cross arm 34 secured to arms 32. A pair of spaced rubber rolls 35 are located on the arm 34 and serve to maintain the work sheet against the platen 15. A plate 36 parallel to end plate 12 is integral with shelf 29 and depends therefrom. The platen shaft 14 extends through a sleeve 37 extending between plates 12 and 36.

A pair of spools 38 are mounted on the upper part of the frame 10. A stationary upstanding type guide 39 is carried by the frame 10 at the approximate center thereof, and its effective guideway is located adjacent the platen 15. A ribbon vibrator 40 is also carried by the frame 10 and is located between the guide 39 and platen 15, and an inked ribbon 41 passes from one of the spools 38, through the vibrator 40 therefor to the other spool 38. Upon actuation of any key 42, the vibrator 40 raises a portion of the ribbon 41 carried thereby to effective printing position and in the normal writing line when it is struck by the particular type actuated by any one of the particular keys 42. After the type strikes the ribbon 41, the type returns to its original position and the carriage moves automatically a letter space from right to left, and the vibrator returns the ribbon below the writing line.

According to my invention, the usual right hand platen knob of this particular conventional front strike typewriter may be eliminated so that the space adjacent the end of the end plate 13 is free from any long projecting parts or controls. The left hand platen knob may in this instance be provided with an extension 51. With these and other changes, most of which are herein specifically set forth, the typewriter is ready to accommodate the following structure to provide my invention. The modifications and changes required in individual writing machines vary, depending upon its particular structural details and arrangement of parts.

I have shown my invention carried out by adding to the conventional typewriting machine four substantially unitary assemblies of parts, each performing certain functions in supporting and operating the strips. I have designated these four novel assemblies in the drawings and in this description as A, B, C and D.

Assembly A I locate at the right hand and high end of the effective oblique stretch of ribbon, and it includes a pivotally mounted assembly supporting a supply spool, tension imparting means, ribbon guide means and operating adjustments.

Assembly B is located at the opposite extreme end of the carriage, and represents the grip feed device to uniformly feed the ribbons from the supply.

Assembly C is located directly adjacent the left hand end of the platen and carriage, and provides the function of spreading the pack of ribbons thicknesswise at the low end of the effective oblique stretch to paper guiding position, and it also includes a guide to maintain the pack

in widthwise operative register with the writing line.

Assembly D is located also adjacent the end of the carriage near the low end of the effective stretch, and is an arrangement of levers to control carriage return, impart uniform steps of feed to the ribbon, and to line space the work sheet.

The novel unitary assembly A is mounted on and at the right hand end of the carriage 11. The complete unitary assembly A may preferably include a supporting means for a supply of ribbon, which may be a spool of impression transfer material, such as carbon paper or the like, a constantly effective or operative tensioning means which may include a retractor to overcome ribbon slack, and a guiding means to adjust the ribbon in a predetermined path and preferably along such a path that the ribbon will be approximately tangential to the periphery of the platen, and the upper and lower edges of the ribbon equidistant from the axis of the platen, at the extreme right hand end of the stretch. The assembly A includes the added advantage of being adapted to have the location of said high end varied with respect to the horizontal. Suitable adjustments as well as other parts may be included as features of said novel assembly.

In one of its specific aspects, the complete unitary assembly A may include a connector or bracket 52 firmly secured to the end plate 13 and mounted on the outer face thereof. An axle 53, having a hollow, interiorly threaded outer end, is firmly fixed at its other end to the bracket 52. The axle 53 extends outwardly from the bracket 52 and is disposed at an angle to the horizontal. The angle which the axle 53, of the assembly A when mounted on the carriage 11, makes with the horizontal, is approximately equal to the oblique angle the hereinafter described effective oblique stretch of ribbon along the platen, and over its operating range makes with the horizontal so that the effective stretch of ribbon is approximately parallel to the axle 53.

Instead of permanently fixing the axle 53 to bracket 52, a suitable adjustable connection, such as a locking ball and socket joint may be employed therebetween in order that the angular disposition of the axle 53 with respect to the horizontal may be varied at will, which may be desirable in some cases when the angular disposition of the effective stretch of ribbon is greatly varied in the course of typewriter operation. A supporting plate 54, having a bushing 55 welded to the underside thereof and passing through openings in depending ears 56 of plate 54 is pivotally mounted on the axle 53. The bushing provides a suitable bearing on axle 53 to vary the position of the supported parts which may be pivoted thereabout and is retained in position by a washer 57 and a screw 58 which bears against washer 57 and is in threaded engagement with the interiorly threaded outer end of axle 53. The support 54 may be a substantially flat plate including a forwardly projecting guide supporting extension 59, a support position limiting extension 60 and a finger piece extension 61. The extension 60 extends rearwardly of the support 54, is bent slightly upwardly and is provided with an opening through which rod 62 passes. Rod 62 is threaded along most of its length and is firmly anchored to the right hand end of the tabulator rack 19 from which it extends downwardly. Two pairs of nuts 63, 64, 65

and 66 are threaded on the rod 62, with one pair 64 and 63 acting as the upper stop for extension 60 to limit the lower position of the front end of support 54 and the other pair 65 and 66 acting 5 as the lower stop for extension 60 to limit the upper position of the front end of support 54.

Mounted on that portion of the bushing between connector bracket 52 and ear 56 is a coiled spring 67 having one end anchored to the bracket 10 52 and its other end extending in the form of a straight section and having its free extremity located against the under face of extension 59. The coiled spring 67 is so adjusted that it at all times, when the assembly is mounted, tends to 15 force the front of the support 54 to its uppermost position and the extension 60 against the lower pair of stop nuts 65 and 66.

A small flange 68 extends downwardly from the extension 59 at the inner side thereof. A 20 locking pin 69 is anchored in the flange 68 and extends towards the end plate 13. A latch 70 is pivotally mounted on a stud affixed to the end plate 13 and is retained on the stud for free pivotal movement by screw 71. Wrapped around 25 the stud is a coiled spring 72 having one end anchored to the end plate 13 and its other end anchored to the latch 70. This spring 72 tends at all times to force the latch 70 towards a stop 73 therefor against which it bears when it is inoperative. The characteristics and positions of the pin 69 and latch 70 may be so chosen that the latch 70 is automatically operable to lock the supporting plate 54 in lowered position by appropriate movement of the support 54.

30 The latch 70 has a hooked upper end and its lower end terminates in a fingerpiece 74. The upper and inner face 75 of latch 70 is in the form of an angular cam. Upon merely finger pressing the extension 61, the plate 54 is rotated about 35 axle 53 and the pin 69 upon lowering of the front part of support 54 bears against the inner cam face 75 of hook 70.

When the front end of the support 54 is in its lowermost position determined by the position of stop nuts 63 and 64, the pin 69 is located below the lower extremity of cam face 75 at which time the spring 72 causes a counter rotation of latch 70 to engage the pin 69 in the hook portion of the latch to lock the plate 54 in that 40 position. When it is desirable to change the location of the front of plate 54 from its lower to its upper position, the fingerpiece 74 is pushed upwardly to rotate the latch 70 against the action of the spring 72 whereby the pin 69 is disengaged 45 and the spring 67 forces the front end of the support 54 to its upper position against stop 73. The stop nuts 65 and 66 against which the extension 59 bears, automatically determine the upper 50 position of the front of plate 54.

60 Carried on the plate 54 is a flat serrated disc 76 having uniformly spaced teeth 77. The diameter of the disc is preferably greater than the diameter of a full spool of ribbon to be mounted thereon. The disc has an opening in the center 65 thereof and that portion of the disc defining the opening has a circular recess accommodating a complementary formed axis in the form of a small disc 78 located in said opening and having a portion thereof located in said recess. The disc 78 is maintained in fixed position by a screw extending through an opening in the support 54 and threadedly engaging disc 78. The disc 78 maintains the disc 76 in position and the disc 76 70 is free to rotate about disc 78 as an axis and 75 rests upon the upper face of support 54. Two

diametrically disposed upstanding pins 79 are anchored to the disc 76 and serve to retain a spool of ribbon on disc 76.

At the outer end of the extension 59 there is 5 mounted a cylindrical ribbon guiding roller 80 which has a longitudinal opening in the center thereof accommodating a screw 81. The screw 81 is mounted substantially perpendicular to the support 54 and is threaded into extension 59 and secured thereto by a locknut. This roller 80 has upper and lower circular retaining flanges 82 between which the ribbon may pass and it is free to rotate about screw 81. The distance between 10 the flanges 82 is just a little greater than the width of the ribbon guided thereby. When the assembly 15 A is mounted and the front part of the support 54 is in its operative position, the roller 80 is located adjacent the right hand end of the platen 15 and is preferably disposed at such an angle as shown in Figure 32. 20

At an opening in the rear part of support 54, a short bushing 85 is fixedly secured to said support 54 and depends therefrom. A gear 86 rests on the upper face of the support 54 and has a depending interiorly threaded center boss 87 and an upstanding lug 88 integral therewith. The boss 87 is located in said bushing 85 and is maintained in position by a screw 89 threadedly engaging the interior threaded portion of boss 87. The gear 86 may be rotated about the bushing 85 25 and its location maintained otherwise fixed. The gear 86 is a small circular disc having a plurality of spaced uniform teeth 90 uniformly disposed about approximately two-thirds of its circumference, and a stop in the form of a double or triple width tooth 91 at one extremity of the series of teeth 90, and with a large space between the tooth 91 and the first tooth 90 of the series at the other extreme. 30

The location of gear 86 and the size and spacing of the teeth 90 are such that the teeth 90 35 may mesh with the teeth 77 of the disc 76. It is preferable that the diameter of gear 86 be materially less than that of gear 76 and the ratio 40 may be as small as one to four. 45

A modified Z bracket has one of its legs 92 resting on support 54 and secured thereto by screws 93 and the other leg 94 thereof extends over the gear 86 and is spaced therefrom by its 50 connecting web 95. Directly over the center of gear 86, the leg 94 has a vertically disposed opening accommodating an interiorly threaded hollow boss 96 integral with a circular tension adjusting plate 97 located between the lower face of leg 55 94 and the upper face of lug 88 and spaced therefrom. A retaining screw 98 threadedly engages the interior of the boss 96 to maintain the plate 97 in position, while the plate 97 is free to rotate. The diameter of plate 97 may be approximately 60 the same as that of gear 86 and it has a plurality of vertically disposed openings 99 arranged in a circle through its thickness and near the outer periphery thereof. A flanged plunger pin 100 having a knob 101 at the upper end thereof extends through an opening in the leg 94. A spring 102, surrounding said plunger 100 and bearing against the upper shoulder of the recess in the leg 94 and against the flange of pin 100, tends at 65 all times to force the pin downwardly. The lower limit of the pin 100 is determined by the knob 101 and the upper face of leg 94 when the pin is 70 in effective or operative position. The pin 100 is so positioned with respect to the openings 99 that the pin may enter any one of them, upon rota- 75

tion of plate 97, to lock said plate against rotation.

Depending from said plate 97 near the outer edge thereof is a short pin 103. A wound flat spring 104, with a looped outer end, is located between gear 86 and plate 97. The inner end of the spring 104 is anchored in a vertical slot in the lug 88 and the pin 103 is located in the loop end so that winding or unwinding of the spring 104 depends upon rotation of gear 86 and plate 97 with respect to each other.

According to my invention the unitary assembly A as described may include all of the elements except rod 62 together with nuts 63, 64, 65 15 and 66 and latch 70 together with stud, screw 71, spring 72 and stop 73, and may be assembled as a unit and then affixed to a writing machine in its appropriate place and position. In addition the axle 53 and bracket 52 together with the 20 retaining screw 58 and washer 57 may be omitted as parts of the assembly A. These parts may first be fixed to the typewriter and the remainder of the assembly may as a unit be assembled and then mounted directly as a single unit on said 25 axle 53.

Mounted on the large disc 76 is a spool of one, two, three, four or more strips or ribbons of impression transfer material wound on a core 105 having openings through which the upstanding 30 pins 79 pass. When the front of the mounted assembly A is in its upper or operative position, the support 54, disc 76 and spool of ribbons are disposed as shown in Figure 3, with the support 54 and the parts supported thereby inclined rearwardly downward from the front extremities thereof and also inclined downwardly from the extreme right-hand points thereof toward the plate 13 as hereinbefore described, and the axis of the guide roller 80 inclines downwardly and 40 forwardly. The ribbon as it passes over said roller will have its edges equidistant from the platen axis and above the writing line along the front of the platen at the extreme right-hand limit of the stretch, so that at normal angular 45 adjustment of the stretch the spool of ribbon will lie in a plane reasonably parallel to the effective stretch of ribbon between the guide roller 80 and a fixed ribbon guide at the left-hand end of the platen, as will be hereinafter described. The 50 fixed ribbon guide at the left-hand end of the platen is below the left-hand end of the writing line and inclines downwardly and rearwardly as hereinafter described, so that a stretch of ribbon between the roller 80 and the said fixed guide 55 will lie in a helical path oblique to and extending across the writing line, with the edges of the ribbon uniformly and equally spaced from the platen along the stretch of ribbon between the said roller and guide.

60 The assembly A having a spool of ribbon mounted thereon may be adjusted to a particular operating position as shown in Figure 3, by locating the stops 65 and 66 at a selected position on the rod 62. In Figure 3 the operating adjustment shown is such that the guide roller 80 is raised to a position where the effective oblique stretch of ribbon is barely in register with the maximum writing line. The rear portion of the platform 54 is tilted downward, and the outer 65 end of the axle 53 is tilted upward and is parallel with the effective oblique stretch of ribbon, and the ribbon strips extend directly from the spool, over the guide 80, and will meet the platen and extend along the platen in an effective spiral 70 oblique stretch. The ribbon is therefore guided 75

to the effective helical stretch in a natural and undeformed path in such a manner that the upper and lower edges of the ribbon are at all points along the platen approximately equidistant from the axis of the platen.

5 By changing the position of the stops 65 and 66, the position of the platform 54 and consequently the guide 80 can be changed. Providing the guide roll 80 is not raised excessively there will be a reasonable approach to the aforesaid desired meeting of the strip at the end of the platen, sufficient to effectively conform the major portion of the effective stretch to the platen in a helical manner.

10 By adjusting the stops 65 and 66 so that the 15 guide 80 is maintained in a higher vertical position than shown in Figure 3, the effective oblique stretch of ribbon will be at a greater degree of angle relative to the writing line than is illustrated in Figure 3 and shown in detail in Figure 20 20, and the effective stretch of ribbon will no longer be in effective working register with the maximum writing line, but will remain in working register with only a portion of the writing line and particularly the left hand portion of the 25 maximum writing line, and the angle may thus be varied without disturbing other portions of the ribbon carrying structure.

30 The action of spring 67 is such that it tends at all times to maintain the platform 54 in operative upward position, and tends to return the platform to original operative position after any displacement.

35 The effective oblique stretch of ribbon may be removed from operative position by merely depressing the finger piece 61 to rotate the platform 54 and supported parts about the axle 53, and the latch 70 may be used to lock the forward portion of the platform and the guide 80 in downward position, thus swinging the high end of the 40 effective stretch downward about the low end guide means hereinafter described, as a pivot point. The stretch is then disposed as shown in Figure 25 and in dotted lines in Figure 2, below the field of the writing line and slightly away 45 from and forward of the platen.

50 When the spool and platform 54 are in operative position as shown in Figure 3, and ribbon is fed from the spool and along the platen 15, both the spool and disc rotate in a clockwise direction. Assuming that the teeth of disc 76 and gear 86 are in mesh as shown in Figure 14, just before the ribbon is fed, then as ribbon is fed from the spool a counterclockwise rotation of gear 86 driven by gear 76 is positive and the 55 spring 104 is further wound until the last tooth 90 of the gear 86 is in position where there is no positive mesh as shown in Figure 13, when the teeth of gear 76 merely strike said last tooth 90 and chatter thereby and impart a slight vibratory rotation to gear 86 and thus the gear 76 is always subjected to a counter-clockwise force. If the ribbon tends to develop any slack because of overspin of the spool, the spring 104 causes a 60 counter rotation or a clockwise rotation of the 65 gear 86 whose teeth positively mesh with those of gear 76 to cause gear 76 to counter rotate in a counter-clockwise direction to rewind the ribbon on the spool and take up any slack.

70 The degree of counter rotation is limited by the 70 enlarged tooth 91 which acts as a stop against the teeth of gear 76 to prevent a too great counter rotation of gear 86, and the spring 104 cannot unwind beyond a certain degree. In this manner a retractive tension is constantly imparted to the 75

effective ribbon stretch extending from the supply spool by the positively meshing gears 76 and 86, with the gear 86 having a portion thereof where the teeth have been omitted so that only a certain 5 degree of tension may be applied and the gear 76 may rotate without causing more than a limited cumulative rotary movement of the gear 86, although a counter rotative force is always applied to the gear 76, and in addition the amount of 10 retraction due to ribbon breakage or overspin of the spool is limited by the stop 91 which also prevents the spring 104 from completely unwinding, as indicated in Figure 15. In some instances 15 it is desirable to vary the degree of tensioning on the spool and strip as may be the case when the spool gets smaller in diameter during use. This may be readily accomplished by raising plunger pin 100 out of the opening 99 and rotating the plate 97 and reinserting the pin in the 20 appropriate opening 99.

The novel unitary assembly B I prefer to dispose at the left hand end of the carriage 11. The assembly B primarily serves to feed the ribbon from the supply spool against the action of the 25 hereinbefore described tensioning and retracting device and includes a frame or bracket consisting of a side 120, a top plate 121 integral therewith and disposed thereto at an angle slightly less than 90°. Also integral with said side plate 120 and 30 extending outwardly therefrom is a bottom plate 122 parallel to plate 121. An opening in the side 120 has a bushing 123 located therein and extending from side 120 to which it is firmly fixed.

The frame or bracket is so mounted that the 35 bushing 123 is pivotally mounted on the left hand end of the platen shaft 14 and is concentric with sleeve 37 and shaft 14, and the side 120 is adjacent the outer face of plate 36. A retaining and lock screw 124 extends through an arcuate slot 40 125 in side plate 120 and makes threaded engagement with a tapped opening in the plate 36. Thus the frame and the hereinafter described parts supported thereby may be swung about shaft 14 as an axis and screw 124 is employed to 45 lock the assembly in any desired adjusted position, and to properly match the oblique and helical path of the ribbon.

A driving shaft 126, having a ratchet gear 127 integral therewith and located between the ends 50 thereof, has its lower portion extending through an opening in the front left hand portion of the top plate 121. Mounted for free rotation on the upper part of shaft 126 is a drum 128 resting on gear 127 and having an upper flange 129 and a 55 lower flange 130 providing retaining walls for a flexible element 131, such as a chain or cord, having one end secured to the drum. This flexible element 131 may be wound one or more times around said drum and provides a driving connection for the shaft 126. The drum has a recess in its upper end accommodating the head of a screw 132 threadedly engaging the shaft 126 to retain the drum on shaft 126 and thus provide an upper bearing for the drum upon rotation 60 thereof. A more shallow and larger diameter recess is provided at the top of the drum and located therein is a disc 133 having a slotted shaft 134 and integral therewith and extending upwardly therefrom. The disc 133 is firmly anchored to the 65 drum by screws which pass through the disc and make a threaded engagement with the drum.

A flat spiral spring 135 is wound around shaft 134 and has one end located in the slot of the shaft 134 and anchored thereto. The other end 70 75 of the spring 135 is anchored to an upstanding pin

136 stationary with respect to plate 121. The upper end of the shaft 134 is of reduced diameter to accommodate a guard plate 137 which is spaced from the spring 135 and is retained on said shaft by a screw, which makes threaded engagement therewith.

Fixedly secured by rivets to said top plate 121, depending therefrom and surrounding said shaft 126 is a stationary bushing 138 terminating above the lower limit of said shaft. A driving sleeve 139 having a flange gear 140 integral therewith at the upper end thereof is rotatably mounted on the stationary bushing 138 and is fixedly coupled to the shaft 126 by pin 141 located below the lower extremity of bushing 138. Fixedly mounted on the sleeve 139 is a rubber or other appropriate frictional type driving sleeve 142. I have found live rubber to be admirably suited for my purpose.

Pivotedly mounted on the under face of the top plate 121 is a pawl 143 and pivotally mounted on the under face of drum flange 130 is a pawl 144. Springs 145 and 146 are respectively mounted on plate 121 and flange 130 and bear respectively against the pawls 143 and 144 to at all times force them respectively towards the gears 140 and 127. By pulling on the flexible element 131 the drum 128 is rotated in a counterclockwise direction against the action of spring 135 which is further wound thereby.

Upon rotation of the drum in this counterclockwise direction, the pawl 144 engages a tooth of gear 127 and rotates the shaft 126 together with the gear 140, sleeves 139 and 142 coupled therewith in the same direction. When this takes place the pawl 143 is inoperative and the gear 140 rotates by the pawl 143. When the force is removed from the flexible member 131, the spring 135 causes the drum to rotate in a clockwise direction and during this clockwise rotation, the pawl 144 is inoperative and the pawl 144 slips over gear 127, 40 but the pawl 143 engages a tooth of the gear 140 to prevent counter rotation of the shaft 126, gear 140 and sleeves 139 and 142. With this arrangement of parts, the flexible member 131 may be pulled outwardly to rotate both the drum 128 and 45 gears 127 and 140, and upon removing the force from this element 131, the spring 135 automatically counter rotates the drum 128 to rewind the element 131 thereon and the gear 140 is prevented from rotation by pawl 143 during counter rotation of drum 128. Thus, while the drum 128 may 50 rotate in both directions, the shaft 126, sleeve 139, gear 140 and sleeve 142 may rotate in one direction only.

A yoke or bracket having flange side arms 150 and a sleeve cross arm 151 is mounted between top plate 121 and bottom plate 122 with the sleeve cross arm pivotally mounted on rod 152 fixedly mounted between the top plate 121 and the bottom plate 122 by an elongated screw 153. A rod 154 is fixedly secured to the flange arms 150 between which it extends. Rotatably mounted on said rod 154 is a driven sleeve 155 having a flange gear 156 integral therewith at its upper end. The length and the outside diameter of the sleeve 155 and its flange gear 156 are equal to the corresponding dimensions of the sleeve 139 and gear 140.

Fixedly mounted on the driven sleeve 155 is a driven sleeve 157 of the same composition as sleeve 142. These sleeves 157 and 142 are exactly the same in all respects except that the external diameter of the sleeve 157 is slightly less than the external diameter of the sleeve 142. In addition both flange gears 140 and 156 are of exactly the 75

same diameter and pitch so that when they are in operative position a complete revolution of the driving flange gear 140 causes a complete revolution of the driven flange gear 156. With 5 this particular construction the rate of travel or the linear velocity of the outer face of the rubber sleeve 142 is always slightly greater than the rate of travel or linear velocity of the outer face of sleeve 157, upon rotation of the sleeve 142, while 10 the angular velocities of the sleeves 142 and 157 are equal.

A wire spring 158 consists of a modified U shaped portion having a number of windings on each leg which surround the upper and lower 15 portions of the rod 152 located above and below the limits of the sleeve cross arm 151 of the yoke and between the interior faces of the top plate 121 and the bottom plate 122. The spring terminates in a pair of straight sections extending 20 from the outer windings. The outer ends of these sections are anchored to the rear parts of the plates 121 and 122 and when so mounted the cross bar of the U section bears against the plate of the yoke which connects the sleeve arm 151 and 25 the flange section 150 thereof and tends at all times to rotate the yoke about its axis to force the rod 154 together with its supported parts towards the rubber sleeve 142. In this manner the 30 flange gears 140 and 156 are maintained in positive mesh during the operation of the feeding mechanism and the rubber sleeves 142 and 157 are forced towards each other at all times by this spring.

A deflector plate 159 is secured to the outer face 35 of the yoke at its upper end, with the plate being welded to the yoke along a line extending rearwardly downward to guide and deflect the ribbon fed by the sleeves 142 and 157 so that the free ejected strips will be suitably deflected and slightly 40 flared or twisted to freely pass under the platen shaft extension 51 and to a wire bracket or support 160 carried by and depending from the tabulator rack 19. The bracket or support 160 extends below the lowest point of the sleeves 142 45 and 157 and has a side arm extending forwardly about one half of the width of the carriage 11 and along said carriage, but spaced a distance outwardly therefrom corresponding to the width of the top plate 121.

Anchored in the top plate 121 is a bushing 161 50 in which is rotatably mounted a shaft 162 having a knurled head 163 at one end and a cam 164 at its other end below the plate 121. By rotating the knurled head 163 in one direction cam 55 164 presses against the yoke and forces the yoke to rotate about rod 152 to separate the meshing gears 140 and 156 and move the rubber sleeves 142 and 157 from each other, as shown by dotted line in Figure 33. Carried by the bushing 161 60 is the pin 136.

When the cam 164 has been rendered inoperative, and the knob 163 is released, the yoke carrying the sleeve 157 and gear 156 is pressed by spring 158 towards the sleeve 142 so that the 65 gears 140 and 156 located above the effective or gripping surfaces of sleeves 142 and 157 are in positive meshing relationship. The shaft 126 and rod 154 and the sleeves 142 and 157 are positioned forward of the axis of the platen 15 a predetermined distance to deflect the path of the strips of ribbon outwardly from the platen axis a predetermined distance. The shaft 126 and rod 154 70 are always parallel and as mounted in their retaining bracket are inclined downwardly and inwardly towards the end plate 12.

This inclination is preferably such that the axes of shaft 126 and rod 154 are approximately perpendicular to the path of the effective oblique stretch of ribbon. The bracket is so disposed about its axis and so locked in position by screw 5 124 that the axes of shaft 126 and rod 154 are approximately perpendicular to the path of the effective oblique stretch of ribbon. The bracket is so disposed about its axis and so locked in position by screw 124 that the axes of shaft 126 10 and rod 154 are inclined also rearwardly downward. This second adjustment is such that the shaft 126 and rod 154 are approximately parallel to a line tangential to the platen 15 at the extreme left hand end of the platen subjacent the 15 longitudinal center line of the strip of ribbon.

As shown the so inclined shaft 126 and rod 154 are so located with respect to each other that, while the gears 140 and 156 are in positive mesh, and the rod 154 is located closer to the end plate 20 12 than shaft 126, rod 154 is also located slightly rearwardly of shaft 126. Whatever may be the particular position of the axes of the driving and driven rubber sleeves, depending on the location of the entire assembly, it is preferable that 25 they be so located with respect to each other that one rubber sleeve makes a firm gripping contact with the surface of a strip of ribbon while the other sleeve makes a contact, but one which allows some slippage, especially when two or more 30 strips are fed from a single spool of multiple strips of ribbon.

When a single spool 165 of three strips or separate plies of ribbon is mounted on the core 105 35 so that the spool 165 and core 105 rotate in unison, this multiple ply spool together with its core is supported by the disc gear 76, with the pins 79 extending through openings in the core 105. A stretch of strips 166, 167 and 168 with coated 40 face towards the platen extends from the spool 165 and the free ends of the strips may be fed by actuation of feed rolls or gripping sleeves 142 and 157. A counter rotative force is constantly applied to the disc 76 and spool 165 by the spring 104 acting through the small tensioning gear 86 45 at all times, and this force will be imparted to at least one of the strips 166, 167 and 168. If the ends of said three strips are firmly held together and a long stretch of all the strips is, pulled from the supply 165, it will be found that 50 the stretch of strip 168 farthest from the platen is longer than the stretch of 167 and the stretch of 167 is longer than the stretch of 166 because the diameter of the roll of strip 168 is just slightly greater than the roll of its subjacent strip 167 55 and the diameter of the roll of strip 167 is just slightly greater than the roll of its subjacent strip 166, and this condition exists for every turn of these three strips on the spool. Therefore, if the strips were all fed from the spool at the same rate 60 of speed, the length of the outer strip 168 from supply spool to the feed rolls would soon be noticeably greater than the subjacent strips 167 and 166 and the strip 166 would probably be the only strip under tension while the other two strips 167 65 and 168 would be loose and would buckle or sag between the supply spool 165 and rubber sleeves 142 and 157.

To prevent this condition of looseness and buckling of the outer strip 168 and to maintain 70 all of these strips constantly under approximately even tension during operation when the diameter of the spool 165 progressively decreases, I employ a preferred relationship of parts.

The diameter of the rubber sleeve 142 is greater than the diameter of the sleeve 157 so that upon 75

rotation of the said sleeves, one by the other, the linear speed of the sleeve 142 is greater and about 2% greater than that of sleeve 157. Thus the difference in the speed of travel of the sleeve 142 when compared with the speed of travel of the sleeve 157 is always greater than the difference in the speed of feeding of outer strip 168 compared with the speed of feeding of the inner strip 166 at any moment, so that in effect the difference between the linear speeds of travel of the sleeves 142 and 157 is over compensatory by an amount above the critical compensatory difference in speeds, while the angular speeds of the sleeves 142 and 157 are equal. The so proportioned sleeves 142 and 157 are so located with respect to each other that the surface of the sleeve 157 is in contact preferably with the coated inner face of the inner strip 166 and this area of contact is materially greater than the area of sleeve 142 in contact preferably with the uncoated outer face of the outermost strip 168, with the strip 167 being located between strips 166 and 168. This stretch of three strips, over its entire width is in contact with the sleeve 157 along a material portion, say about $\frac{1}{4}$ of its circumference, while the sleeve 142 is in contact with the outer face of strip 168 along only a narrow line.

Since the coated surface of the strip 166 is roughened due to type impact and since it is maintained under pressure against the sleeve 157 over a comparatively large part of the area of sleeve 157, there is provided a firm and efficient grip between the sleeve 157 and that portion of strip 166 in contact therewith. By providing the preferred grip between sleeve 157 and strip 166, slippage of the strip 166 over sleeve 157 is reduced to a practical minimum. The strip 168 on the other hand makes contact with the sleeve 142 along only a small portion of the area of sleeve 142 and the plain uncoated surface only of the strip 168 contacts sleeve 142. The outer ply 168 therefore develops more slippage over the sleeve 142 because the relatively smooth, uncoated side of the ribbon 168 is in contact with a narrow band or line of sleeve 142.

Thus when the flexible chain 131 is pulled the flange gears 140 and 156 are in positive mesh and the sleeves 142 and 157 rotate to pull the ribbons 166, 167 and 168, and all of the strips are constantly maintained under tension by the retractor on platform 54. For each full actuation of the chain 131, the sleeve 142 travels an amount greater than the travel of sleeve 157 by an amount greater than the difference in length of the strip 168 paid out from the spool compared to the length of the strip 166 paid out from the spool. However, the rotating sleeve 142 slips slightly relative to the uncoated face of strip 168 as it drives this strip 168 through the pressure rolls, and at any time that the sleeve 142 tends to drive the strip 168 too rapidly as related to strips 166 and 167 all the tension is imparted to strip 168 which aids in creating additional slippage between sleeve 142 and strip 168 and in again equalizing the tension to all three strips.

The novel assembly C is mounted at the left hand end of the carriage which represents the low end of an effective stretch of ribbon. The assembly C serves essentially as a thicknesswise separator for the strips and also to guide the strip pack widthwise, and is preferably mounted between the feeding roller assembly and the left hand end of the platen 15. As shown in Figure 11, the assembly C comprises a rugged and rigid main frame 170 including an elongated arm 171,

a short arm 172, guideway arms 173 and 174, a lug 176 having an opening 175 therein, and an enlargement 177 at one end of the arm 171. The arm 172 is integral with the arm 171 and depends therefrom at approximately right angles thereto. The guiding arms 173 and 174 are integral with arm 171 and extend outwardly therefrom at approximately right angles to the inner face thereof. These arms 173 and 174 are spaced from each other and have square openings therein, with the openings in one guideway aligned with the corresponding openings in the other guideway. The distance between the opposing faces of guideways 173 and 174 determines the distance that the slotted strip carrying rods, hereinafter described, may be pulled out from their original position. The enlargement 177 has a recess at the front face thereof defining a guide slot with a bearing face 178 at right angles to the length of arm 171, and a pair of forwardly projecting guide lugs 179 determining the length of the guide or slot. These lugs are spaced from each other a distance slightly greater than the width of the strips 166, 167 and 168.

Adapted to slide in the guideway openings are strip separators 180, 181 and 182. Each separator consists of a square elongated rod 183 extending through a pair of corresponding openings in the guideway arms 173 and 174 with a stop pin 184 anchored to the rod 183 at a predetermined point thereon and between arms 173 and 174, a slotted rod 185 disposed at right angles to the rod 183, a finger piece 186 extending downwardly from said rod 183 and an anchor pin 187 located at the rear extremity of rod 183. The length of the rod 183 of separator 180 is slightly greater than the length of rod 183 of separator 181 and the length of rod 183 of separator 181 is slightly greater than the length of rod 183 of separator 182, so that the slotted rod 185 of separator 180 may be located at a slightly greater distance from the axis of the platen than is the rod 185 of separator 181 and the rod 185 of separator 181 may be located at a greater distance from the axis of the platen than is rod 185 of separator 182 when the assembly is mounted.

Extending outwardly from the lower end of arm 172 and firmly secured thereto is a rod 188 which is parallel to the guideway arms 173 and 174. Firmly anchored to said rod 188 along the length thereof are the lower straight ends of three springs 189. Each spring 189 is a spring wire, bent at its mid section in the form of a coil and the upper straight end sections of the springs 189 are anchored to the anchor pins 187. When the separators are in their full line positions shown in Figure 11, the springs 189 exert a force thereon tending to pull them backwardly and thus the separators are maintained in this position by virtue of the springs 189 and the stops 184 which are forced against guideway 173.

By pulling on the finger piece 186, a separator may be pulled outwardly from the frame and the rod 183 slides forwardly in the openings in the guideway. The pull is exerted against the action of the spring 189 until it passes the dead center and then the spring automatically forces the separator farther forwardly until the stop 184 strikes the rear of guideway 174 and the spring maintains the separator in this position shown in dotted lines in Figure 11. Thus the spring is adapted to maintain the separator for an indefinite period of time in either its rear or forward position, at the operator's option, and these springs maintain the strips in either position in

spite of the tension of the ribbon strips threaded through the separating elements, which would otherwise tend to force the separator rods to an intermediate point.

- 5 As shown in Figure 10, the lower portion of the sleeve 37 may be cut away and the assembly C as hereinbefore described may be pivotally mounted on the end plate 12, about a stud 190 which is affixed to the end plate 12, and which 10 extends through the opening 175 in the lug 176. A spring 191 is connected at one end to the end plate 12, and at its other end bears on the lug 176, and tends at all times to swing upward the forward end of assembly C including the guiding 15 lugs 179, about the stud 190 as a pivot. A bracket carrying an adjustable screw stop 192 is carried by the end plate 12, with the lower outer face of arm 172 bearing against the free end of the stop 192. This adjustment limits the vertical 20 position of the forward portion of the assembly C including the strip guiding slot, and the effective position of the guide may therefore be varied and is always spring maintained against the adjusting screw 192. Instead of mounting the assembly C on the end plate 12, it may be mounted 25 pivotally on the platen axis 14 and it also may be rigidly connected to side plate 120 so that both assemblies B and C may be swung in unison. Optionally the assembly C may be rigidly mounted 30 to end plate 12 and no adjustment provided.

The assembly C is preferably so mounted on the end plate 12 and so adjusted by adjusting screw 192 that the rods 183 are parallel to a line drawn from the center of the rod 154 and extending diametrically through the axis of shaft 14 with said line being perpendicular to said shaft. The slotted strip-engaging rods 185 are so disposed with respect to the rods 183 that they are parallel to the shaft 126 and rod 154. However, the normal position of the assembly C is such that the straight bearing face 178 of the guide and the slots in the rods 185 are parallel to a line approximately tangential to the platen at the extreme left hand point of the platen 45 subjacent the longitudinal center line of the strip. The bearing face 178 is preferably located near the left hand end of the platen 15 and is adjacent the end plate 12 and is moderately beyond the extreme left hand margin of writing, so that the strips extend directly from the extreme left hand end of the platen in a straight line over the guide bearing face 178 whose lugs 179 prevent vertical displacement of the pack of strips, 50 and from the bearing plate 178 the strips extend in the same straight line through slotted rods 185 and then bend and extend to the feeding sleeves 142 and 157. The slots in rods 185 are diagonally disposed outward away from the end plate 12.

60 The outermost strip 168 is located in the slot of the separator 180 farthest from the platen axis and closest to the end plate 12 and the innermost strip 166 is located in the slot of the separator 182 closest to the platen axis and farthest from the end plate 12, with the intermediate strip 167 located in the slot of the separator 181.

In my construction it is preferable that the 70 distance from the axis of the platen 15 to the slots of the rods 185 and to the bearing face 178 be approximately the same as or just slightly less than the radius of the platen 15. The disposition of the bearing face 178 is rearwardly 75 downward and below the writing line, while the

disposition of the guide 80 is rearwardly upward and above the writing line when the spool 165 is in operative position.

As shown in Figure 6, the three ply ribbon pack extends in a straight line over the bearing face 178 and between the lugs 179 and through the slots of separators 180, 181 and 182 where the ribbons are deflected outwardly from the axis of the platen and away from the separators to the sleeves 142 and 157. These sleeves 142 and 10 157 are located in the manner hereinbefore described so that the pack of ribbons bear against the sleeve 157 over a large portion of the area thereof. The location of the sleeves 142 and 157 from the axis of the platen 15, the location of the rods 185 from the axis of the platen 15 and the location of sleeves 142 and 157 with respect to each other and with respect to rods 185, and the distance between the opposing faces of guides 173 and 174 are so chosen that when the slotted rods 185 are in their maximum spaced positions from the platen 15, as shown in dotted lines in Figure 6, the length of the strip path from the spool to the ejector rubber sleeve 142 is approximately equal to the length of the ribbon path between the same two points when the strips are in their position closest to the platen as shown in full lines in Figure 6. Thus, no one strip 166, 167 or 168 may be subjected to a materially excessive tension, and no strip may for any appreciable length 20 25 30 of time be without tension.

When all three strips are in the outward position, they are under equal tension. When one of the separators is pushed back to its original position, the three strips are even then under the same tension because the length of the strip paths are all approximately the same.

The deflection in the path of the ribbon strips after they have passed through the slotted sections 185 is so chosen as to assist in opening or spreading the tensioned strips with little strain on the strips or distortion in their path. The position of the gripping sleeves 142 and 157 is such as to provide a center or pivot point about which the relatively short stretch of strips is 40 45 50 55 60 65 70 75 80 85 90 95 100 swung in the spreading operation, while the guide 80 at the opposite end of the effective oblique stretch acts as a pivot point about which the long effective stretch is actuated in the thicknesswise spreading operation. The pack of ribbons is maintained in its proper widthwise path by the two common guides 80 and 179, and the separators 180, 181 and 182 are placed beyond the lower guide 179 so that when the separators are actuated the strips are drawn away from the common guide 179 but when the separators are forced inwardly the widthwise position of the strips will again be governed by the guide 179, and the necessity for a plurality of separate widthwise guides is eliminated by placing the separators beyond the main stretch of ribbon maintained between guides 80 and 179.

Still another aspect of my invention is the particular path of the strips 166, 167 and 168. 65. With the elements in operative position as shown in Figures 2, 3, 27, 28, 29, 30, 31 and 32, the front end of the support 54 is maintained in its uppermost position by the spring 61. The spool 165 of three ply strips 166, 167 and 168 is tipped towards 70 end plate 13 and also towards the rear of the carriage in the manner heretofore indicated. The strips 166, 167 and 168 extend upwardly and along the inclined face of the platform 54 and then bend over the cylindrical guide 80 which is 75

inclined in the manner herebefore described and as shown diagrammatically in Figures 27 and 32. From the guide 80, the ribbon extends in a downwardly inclined and helical path along the length 5 of the platen and then in a straight line to the guide face 178 and between the lugs 179 to the separators 180, 181 and 182 and then they follow a deflected path from the separators to the sleeves 142 and 157. As shown in the drawings, the 10 strips extending along the platen are obliquely disposed with respect to the writing line and are located to extend across and cover the entire length of the writing line. Thus the maximum writing line of the typewriter may be covered 15 by an effective oblique stretch of ribbon, although in some instances it may be necessary to cover only a part of the maximum writing line when the work to be done on the machine is to be of a width less than the width of its maximum 20 writing line, which is customary in average typing.

In this latter instance the lower nuts 65 and 66 are located at a lower point on rod 62 and the 25 inclination of assembly A is increased and the lower edge of the ribbon intersects the writing line at a point inwardly from its extreme right hand end. By effective oblique stretch of ribbon, I mean that the obliquely disposed ribbon is located across the normal writing line of the 30 typewriter and that the length and incline of said stretch are sufficient to cover the necessary length of writing line, either the full length of the line or less than the maximum writing line. The guide 80 and the lugs 179 are disposed in 35 such vertical positions with the guide 80 above the lugs 179 to determine the inclination of the oblique angle which the strips make with the writing line. As shown in Figure 27, the inclination of the strips is such that the entire writing 40 line is covered by the strips and the maximum writing line is effectively covered by this oblique stretch of strips. When so disposed the battery of strips makes a contact with the platen 15 at the extreme right hand end, and the strips at 45 this point are substantially as close as possible to the platen at all points across the width of the strips, with the upper and lower edges of the strips equidistant from the platen axis 16. At the extreme high end of the oblique stretch the 50 lower longitudinal edges of the strips are located approximately coincidental with the writing line as shown in Figure 32.

Besides being disposed at an oblique angle to and located in the writing line, the strips are wrapped around the platen 15 in the form of a 55 helix and the strips, independent of work sheet pressure, conform to the cylindrical platen along their effective length as shown in Figures 29, 30 and 31. This insures a snug and compact relationship between the ribbons and interleaved 60 work sheets.

At the extreme left hand end of the obliquely guided pack of strips, the strips pass over the low end guide face 178. At a point very near the guide face 178 as shown in Figure 28 the top edges of the strips are approximately aligned with an extension of the writing line, and the strips are substantially flat in accordance with the flat face 178. The strips are also substantially parallel to a line taken tangentially 70 from a geometrical extension of the platen subjacent the center of the pack of strips.

Figure 29 shows the relationship of the ribbons with the writing line at the leftmost limit of the maximum writing line, with a major portion of 75 the width of the strips being disposed below the

writing line, and only a sufficient portion of the width of the strips projecting upward into the writing line to accommodate typewritten characters which may impact the ribbon at this point.

Figure 30 shows the relationship of the ribbons 5 with respect to the platen and writing line at a midpoint along the maximum writing line, at which point the width of the strips is equally divided above and below the writing line.

Figure 31 shows the relationship of the ribbons 10 with respect to the platen and writing line at the rightmost limit of the maximum writing line where a major portion of the width of the strips is above the writing line, and only a sufficient portion of the width of the strips extends downward into the writing line to accommodate typewritten characters which may impact the ribbon 15 at this point.

As shown in Figure 32, the ribbon pack lies flat against the length of roller 80 which is 20 located slightly rearwardly of the face of the platen. The line of meeting of roller 80 and the pack is approximately parallel to a line taken tangentially from a geometrical extension of the platen subjacent the center of the pack. The 25 guide 80 is preferably disposed rearwardly of the face of the platen so that the strips will conform to the face of the platen nearest thereto as efficiently as possible and will meet the platen as snugly as possible over a range of angular 30 ribbon adjustments.

Thus the common widthwise ribbon pack guides, the roller 80 at one end of the stretch and the lugs 179 and face 178 at the opposite end of the stretch, are inclined in opposite directions to the vertical and impart a helical twist 35 to the effective stretch and maintain the taut pack snugly against and obliquely along the platen. Consequently independent of work sheet pressure, the strips along the length of 40 the effective stretch conform to the contour of the platen and tend to be curved as shown in Figures 29, 30 and 31; and the portions of the strips immediately adjacent the guides are flat.

With the strips extending taut between the 45 feed rollers and the supply spool, these strips having only their under faces coated and being strips of carbon paper for example, may be used for making duplicate copies, or only one hectograph carbon strip may be used for making a 50 hectograph original or a single ordinary carbon strip for a photo-offset original. When the machine is to be used with only one strip, the rolls 142 and 157 may have the same outside diameter although the described feed rolls may be employed. The strips may be fed along the 55 effective path above described or may be rendered inoperative by merely swinging the platform with its supported parts to its low position and locking the same in that position, when the upper edges of the strips are below the entire writing 60 line and the typewriter may be used for other work.

Thus a particularly effective inoperative position is had with the least possible disturbance of the ribbon supporting structure and the strips 65 are carried completely out of the way with a short easy movement. The inoperative position is obtained by moving only one of the common guides, which may be common for multiple plies of a pack, and only a slight change in the path 70 of the ribbon pack is necessary and much of the ribbon structure may remain fixed in position during the inoperative adjustment operation. The left hand guide lugs 179 are placed a sufficient distance beyond the left margin of writing

to act as an extended fulcrum point for swinging the stretch of ribbon so that when the high end of the stretch is swung downwardly the portion of the strip covering the extreme left margin of writing is also moved downwardly a short distance and the entire effective stretch is then below the entire field of type impacts.

Another aspect of my invention is the novel assembly D, which includes an element for actuating a line spacer and an element for actuating the drum 128 to actuate the feed rollers 142 and 151, with each element adapted to be operated independently of the other, but both elements adapted also to be operated in unison, and also a paper bail lifter operable during movement of the line spacer. On the forward side of the platform 29 and to the left of stop 31 is a shaft 200 extending through openings in the ends of levers 205 and 208 and in the platform. The lower end 20 of the shaft 200 has a disc 201 attached thereto which disc 201 has a lug 202 depending therefrom on its circumference. A retaining screw 203 is secured to the shaft 200 to retain the levers mounted one above the other on the said shaft 25 above platform 29. An elongated coil spring 204 has one end anchored to the lug 202 and its other end anchored to the platform 29 at a point rearwardly of shaft 200. The lower lever resting on the platform 29 is keyed to shaft 200 and has an 30 elongated arm 205 having a short arm 206 at right angles thereto at the inner end thereof and an upstanding curved arm 207 extending therefrom at the outer end thereof. Slidably mounted on the arm 205 is a collar 215 secured to the outer end of flexible member 131 and having a tightening screw 216 adapted to maintain the collar at any position along the length of said arm depending on the degree of strip feed desired for any full actuation of the lever.

40 The upper lever is mounted to freely rotate about shaft 200 and has an elongated arm 208 located above the arm 205 and of less length than arm 205, and a short arm 209 at right angles to said arm 208 and located above arm 206, and an 45 upstanding curved arm 210 at the outer end of 208. The arm 210 has its lower portion extending upwardly and curving like arm 207, then a portion extending outwardly and then upwardly curving.

50 Mounted in the hollow stop 31 is a coiled spring 211 having one end thereof anchored to said stop and its other end extending in a straight section and having a single coil wrapped around the arm 208. This spring tends at all times to maintain 55 the upper lever in its retracted or left hand position when its short arm 209 bears against stop 30. The outer end of the link 28 is pivotally connected to the end of arm 209.

The pawl carrier 25 carrying the line space pawl 60 is preferably enlarged and has a cam 218 extending inwardly therefrom and under the cross arm 34 of the paper bail.

In operation the upper and lower levers are maintained in retracted position limited by stop 65 30, as shown in Figure 1, by their respective springs 211 and 204. In retracted position the arm 205 is disposed at an angle to the arm 208 because of lug 209, and by applying a force in the direction of left to right to the handle or up- 70 standing arm 207, the lower lever 205 may be moved to its full forward position as shown in dotted lines in Figure 1. The arm 207 may travel clear of the arm 210 to full actuation position.

The lower lever travels through the same arc 75 each time it is fully actuated and the length of

the arc is limited by stops 30 and 31. The upper or line space lever may be fully actuated from its rear full line position of Figure 1 by swinging the same from left to right without moving the lower lever, and the arc through which the line space lever swings is also constant and fixed by stops 30 and 31. Upon initial movement of the line space lever, the short arm 209 rotates in a counter-clockwise direction and the pawl carrier 25 rotates to swing the cam 218 towards the rear 10 of the carriage and this cam engages the cross arm 34 of the paper bail to raise it about its axis.

During initial movement of the line space lever and the cam 218 the line space pawl 26 has been riding on the guard flange 23 and as the pawl 26 15 reaches the inner end of the flange 23, the cam has raised the cross arm from the work sheets a sufficient distance so that the bail does not now pack the work sheets or pinch the ribbons. Upon further actuation of the line space lever to its full 20 position, the pawl 26 rotates ratchet gear 21 and platen 15. Thus before there is any rotation of the platen 15 to line space the same, the cross arm 34 has been swung upwardly about its pivot. Upon release of the line space lever the spring 211 25 returns it, the cross arm 34 and the cam 218 to their original positions. Instead of actuating one lever to actuate the feed rolls 142 and 151 independently of the actuation of the line space lever, it is possible for the operator to actuate both 30 levers by the same motion of the hand. The hand is extended across arm 207 to force the lower lever from left to right and upon movement of the arm in this direction it approaches alongside of arm 210 which is also engaged by the operator's 35 hand and the levers are forced to their full actuation positions by this motion.

When in this position both arms 207 and 210 are still alongside of each other, with the arm 207 being directly below the uppermost curved 40 portion of arm 210. The arc of travel of the lower lever is always greater than the arc of travel of the line space lever and they are so correlated that the above position of the levers at the end of their travel may be attained.

The slide 215 may be moved to various points along the length of lever 205 to change the degree of rotation imparted to the drum 128, and the position of the slide 215 may be such as to provide a considerable degree of rotation, or only a 50 very small rotation depending upon the degree of feed required for various kinds of typewritten matter. When the slide 215 is close to the pivot of lever 205 a greatly increased leverage is available which aids in feeding multiple plies of ribbon 55 against a strong tension. By placing the slide at the pivot point it is possible to so limit the pull of the chain 131 that no cumulative rotation will be imparted to the feed rolls 142 and 157.

A particular use of this carriage ribbon device 60 is the preparation from a carbon paper ribbon of negative hectograph writing, as a master copy for duplicating on the so called "chemical" or "liquid" duplicating machines, which require a master copy written in negative on the reverse 65 side of a work sheet. It is a practical requirement of this work that each character written be impacted from entirely new carbon surface which is possible in this ribbon device by driving the ribbon in long steps of feed which however 70 are maintained within reasonable limits by impacting a plurality of lines across the width of the strips. The arrows in Fig. 22 indicate the length and direction of feed necessary to provide an entirely new carbon surface for each line of writing 75

when the ribbon is arranged at the angle indicated in the said figure.

In order to make such an original negative hectograph copy, a single ply of hectograph carbon paper ribbon slightly over one half inch wide to accommodate several individual lines of writing is wound with its coated side outwardly on the core 105. The spool is mounted on the disc gear 16 with the upstanding pins 79, extending 10 through openings in the core. The plunger pin 100 is raised out of an opening 99 in the adjusting plate 97 and the spring 104 is properly adjusted and pin 100 is allowed to extend into the appropriate opening 99 and thus the tensioning device 15 has been adjusted to provide the proper tension and retractive force for a single ply of ribbon. A stretch of ribbon is drawn from the supply, placed over the guide roller 80, drawn along the carriage, between the lugs 179, over the guide 20 bearing face 178, in a slotted rod 185 and its free end inserted between the feed rolls 142 and 157 which may be opened for this purpose if desired, by the finger wheel 163. The finger wheel is released and the rolls 142 and 157 automatically 25 move towards each other by the action of spring 158 to grip the ribbon therebetween. The rolls are rotated slightly and the ribbon is now ready for use with the uncoated face thereof conforming to the platen over its effective stretch which 30 is obliquely disposed with respect to the writing line and is located in said line to provide a helical or spiral path of ribbon, with the writing line located in said path. The guides 80 and 179 may be adjusted so that the ribbon completely covers 35 the entire writing line. The ribbon will be at an oblique angle to the writing line and will have assumed the oblique and helical path as disclosed in Figures 2, 27, 28, 29, 30, 31 and 32.

Generally when hectograph masters are made, 40 completely new carbon surface for each new line of writing is essential. Consequently a relatively long ribbon feed is necessary.

The slidable collar 215 is positioned well outward along the arm 205 and locked in a pre-determined position thereon with screw 216 so that upon a single actuation of the lower or feed roll actuating lever, the flexible element is pulled out a predetermined amount to rotate the rolls 142 and 157 a predetermined amount to feed 50 therethrough a predetermined amount of ribbon to provide a completely fresh surface for the next succeeding line of writing and so that the next line of impacts thereon will have its lower extremity just slightly above the upper extremity of the preceding line of impacts. The line space adjusting handle 24 is now set for 1, 2 or 3 spaces and the operator is ready to type.

When a negative hectograph master is to be produced, a work sheet is fed around the platen 60 and it will automatically position itself outside the oblique stretch of ribbon, since the oblique stretch is snugly maintained against the platen. The ribbon will therefore be automatically located between the work sheet and the platen, 65 with the coated side of the ribbon in contact with the reverse side of the work sheet.

The operator now types a line of writing on the front of the work sheet with the ink ribbon and the type starts impacting the carbon hectograph ribbon very close to its top edge at the left hand side of the platen. The line of impacts thereon during the typing of a line of writing makes an oblique path along and across the ribbon and the last impression of the line will impress the ribbon 75 near its lower edge at the right hand side of the

platen, thus impacting the ribbon along its width and length. The line having been completed, the operator presses the ribbon feed or lower lever to swing it, and may shortly after starting the swing of this lever also press against the line spacing 5 lever to also swing it.

The continued pressure against the two separate levers will move them about their pivot to produce a feeding of ribbon and a line spacing of the work sheet. Continued pressure against 10 one or both of the levers will cause return movement of the carriage to its limit of return travel. The machine is now ready for a new line of typing, and the ribbon has been fed from the supply spool against a retractive tension force, obliquely 15 downward relative to the writing line and along a helical path, and during actuation of the line space lever the paper bail pressure rolls 35 were lifted to relieve pressure against the work sheet so that any excessive pressure or binding between 20 the work sheet and the interleaved ribbon is eliminated while the work sheet is being fed upwardly in line spacing movement, and thus the ribbon drag and hectograph smudge is reduced 25 to a practical minimum.

If the operator wishes an extra line space between the lines of writing on the work sheet she may actuate only the line spacing lever a second or additional time. The ribbon has been fed say 2" which may be a much less distance than 30 the total length of the line of writing; however, due to the ribbon being as wide as several type-written characters are high, and to the oblique downward feed of the ribbon, the previously impacted portions of the carbon ribbon have been moved sufficiently downward to clear the field of type impacts. A succeeding line of impacts will now be written, causing impression material to 35 again be transferred from the ribbon to the reverse side of the work sheet, and the carbon ribbon will be impacted from its top edge to its bottom edge as before, but the new line of impacts will be just clear of and above the previous line of impacts on the carbon paper. Each time a 40 line of writing is completed both levers are actuated and the work sheet is spaced upward while the ribbon is fed obliquely downward, and the downward direction of ribbon feed tends to maintain it in an accurate path and to overcome the 45 upward frictional force exerted on the strip by 50 the line spaced work sheet.

When the work sheet has been fully typed, it is withdrawn from the machine and all characters on the sheet have been typed from clean and unused carbon surface, while a uniform ribbon feeding of only 2" has occurred for each line of writing typed.

The typist may now wish to write upon a narrower sheet of paper. The new sheet is placed in the machine and guided near the left margin of the carriage, and it is determined that lines of writing will be somewhat shorter than for the previous sheet written. The nuts 65 and 66 will be so adjusted that the guide roll 80 is raised vertically with respect to the writing line. Assembly C may be readjusted slightly in position if desired. Due to this adjustment which increases the degree of the oblique angle the length of the writing line covered by the ribbon is shortened and therefore the ribbon still will be impacted fully across its width from the upper edge thereof to its lower edge.

It should be observed that under ideal conditions all of the devices which support the ribbon are inclined or tilted in conformance with the 75

downward and helical path of the ribbon. The degree of incline selected may be such as to match the degree of obliqueness when the ribbon is adjusted for the longest writing line. It will be seen that if the angle of the effective stretch is increased, by raising the guide roller at the high end of the stretch, the angle of incline of the effective stretch will have been changed, while the angle of incline of most of the various supporting parts will remain the same as before. Therefore the ribbon guides and supports are no longer truly matched to the downward angle of the effective stretch, and will not be unless some provision is made to provide adjustment of all the individual supporting and guiding structures.

This would entail difficulties and complications, and it is found in practice that the degree of the angle of the effective stretch can be changed considerably without introducing so serious a mismatch as to cause serious operating difficulties.

If desired, the various guiding and supporting structures may be so inclined as to most perfectly match an intermediate degree of angle of the effective stretch, that is, to match an operating angle moderately less than the angle used for the longest writing line. It is found that if all parts are designed to match such an intermediate angle, the angle of the ribbon can be increased to write relatively short lines of writing before serious difficulty or distortion is encountered, and also maximum length lines can be written with the ribbon set at a lesser angle, 35 without difficulties of any consequence.

The amount of ribbon feed per line written (assuming the angle has been changed to a greater degree for a narrower work sheet) may be reduced by sliding element 215 somewhat towards shaft 200, as the new and sharper oblique angle does not require as great a spacing of ribbon to lap each new line of impacts on a completely new surface. The sheet is typed as before.

45 The typist may now wish to write upon the typewriter, but omitting the use of the carbon supplementary ribbon. By depressing the finger piece 61 the front end of the support 54 is lowered vertically a considerable extent, swinging the effective stretch of ribbon downward about guide 178 as a pivot. The effective stretch of ribbon is now disposed below the entire writing line in front of the lower portion of the platen, or the paper holding rolls, and no longer hugs the 50 platen snugly but is stretched rather flatwise slightly away from or forward of the platen and the lower edge of the ribbon particularly is out of contact with the platen. The ribbon spool is now in the position shown in Figure 4, and the 55 effective stretch of ribbon is disposed as clearly shown in Figure 26.

The ribbon guide 80 has now been swung to a low position whereby the right hand end of the stretch is lower than the left hand end of the 60 stretch, to fully insure that all effective portions of the stretch are below the field of type impacts and to bring the stretch of ribbon to a position whereby a work sheet will be efficiently deflected between the lowered stretch and the platen during the initial feeding of the work sheet to the machine in a normal manner.

Thus a work sheet now fed around the platen will not automatically position itself outside the ribbon as before, but the leading edge of a work sheet fed around the platen will strike against

the inner surface of the strip of ribbon, which will assist in deflecting the work sheet upwardly between the strip of ribbon and the platen. One or several work sheets are so positioned between the lowered stretch of ribbon and the platen, and the typist may type upon the machine in the normal manner—and it is not necessary or desirable to actuate the lower lever at such time as the stretch of ribbon is held in low position below the writing line. The ribbon is now inoperative and the typewriter may be used for addressing envelopes or any other work where the supplementary ribbon is not required. It will be seen that the guide 80 is maintained in downward position by the latch 70, and when the latch 15 is released the stretch of ribbon will immediately spring back into operating position.

The movable guide 80 may therefore be used as a means of positioning the ribbon between two work sheets. One work sheet may be fed around 20 the platen while the effective stretch is held by the guide 80 in its lowered position and this work sheet will feed between the stretch of ribbon and the platen. Then the stretch may be returned to operative position by raising the guide 80 and a 25 second work sheet fed around the platen which will automatically position itself outside the operative ribbon and the ribbon will thus be interleaved between the two work sheets.

The typist may wish to produce typing of a 30 quality suitable for reproduction by some process involving photography, requiring a very sharp and dense and uniform black master copy. The hectograph ribbon is replaced with a suitable black carbon paper ribbon, with the coated side 35 facing the platen. A work sheet is positioned between the ribbon and platen by actuating the separating finger or otherwise. The ribbon is now disposed outside the original work sheet, with its carbon face in snug contact with the 40 front surface of the work sheet.

By providing a suitable grade of carbon paper ribbon, and a suitable and preferably hard platen, an impression of unusually high quality may be transferred to the work sheet. This is because 45 the carbon ribbon does not vibrate or move during the typing of a series of impressions, as is the case when a carbon paper ribbon is used as a prime or frame carried letter spaced ribbon and fed through the vibrating mechanism in the manner of the normal prime cloth ribbon. Dusting and chipping of the carbon particles is eliminated, and a proper and beneficial working contact between the carbon paper and the work sheet is secured.

55 By utilizing a suitably thin cloth ribbon as well as a suitably thin carbon paper supplementary ribbon, and a suitably hard platen or backing surface, the normal cloth prime ribbon may imprint directly upon the uncoated or back surface 60 of the carbon ribbon. In this case however, the carbon ribbon and not the prime ribbon will provide the useful impression on the work sheet, and the impression on the carbon ribbon afforded by the prime ribbon will in a sense be wasted. However, this expedient proves useful in several ways, providing a visible and legible line of impressions on the carbon ribbon to assist the typist in following her work. This visible line of impressions is carried downward and out of the way upon 70 each actuation of the lower lever. The combination of the two ribbons for a single useful impression has a number of advantages; preventing undue cutting and embossing of the paper ribbon by the sharp type stroke, provides a suf- 75

ficient cushioning of the rapid type impact and protection for the paper ribbon, while retaining a desired sufficiently sharp and uniform and dense carbon paper impression on the work sheet, such as is required for successful photography. It allows moreover, the use of a harder platen than is otherwise permissible, with consequently better and more uniform results.

The cloth ribbon may be omitted, as by disposing it inoperative in stencil position, and the bare type allowed to impact directly upon the carbon ribbon; however, no readily visible line of impressions may now be provided on the back surface of the ordinary carbon paper ribbon. This may be remedied by so treating the carbon ribbon, or so selecting its characteristics, that the bare and uninked type will cause a change in the appearance of the paper ribbon that has been impacted.

When the typist wishes to view all of the work sheet, that is, wishes to see the typed impressions which may be hidden by the suspended stretch of ribbon in actual contact with a portion of the work sheet, the finger piece 61 is depressed sufficiently to lower the effective stretch of ribbon and expose all of the typed impressions on the work sheet, which expedient is particularly useful when it is necessary to "register" the typing with ruling or printed matter on a form sheet. For the typing of such photographic copy, the feed of the ribbon is necessarily long like in hectograph work to insure new and unused carbon surface for each new line of typing.

In the same manner as just described, the typist may wish to type with the carbon supplementary ribbon upon zinc or aluminum sheets for direct offset reproduction on a suitable lithographic press. The requirements of this work are much the same as for photographic copy written upon a paper work sheet.

In the same manner a hectograph carbon paper ribbon may be placed in the machine to provide hectograph impressions on the front side of an original work sheet, and a very superior hectograph master copy produced for reproduction by the gelatin process.

The typist may now desire to type manifolded impressions upon multiple work sheets, which is the use to which carriage carried supplementary ribbons of the past have been confined. In this case she may desire to utilize three ribbons as shown in the drawings. A triple ply spool of normal record carbon paper is placed on a core 105 carried by the pins 79, the ribbons properly threaded along the guides and through the separating fingers, and the free ends of all the ribbons are gripped between the feed rolls. The tension is now adjusted to several times the degree of force that was used to tension a single ribbon, so as to provide adequate tension for each ply of ribbon.

The work sheets may now be mounted on the typewriter. Four work sheets, 1, 2, 3 and 4 may be fanned as shown in Figure 23 and the release key 16 is depressed to move the rear paper holding rolls and the front paper holding rolls 17 away from the platen 15 to allow the sheets to be slid easily between the platen and the paper deflector plate 43 beneath the platen. The sheet 1, which is to be contiguous with the platen is fed ahead of the next adjacent sheet 2 which is ahead of the next adjacent sheet 3, which in turn is ahead of the sheet 4 for the original or ink copy. The carriage is moved to its extreme left limit of travel so that the prime ribbon vi-

brator and type guide are located near the right hand end of the effective stretch which end of the stretch is moved very little when actuating the separators, and an appreciable portion of the stretch is exposed and can be moved thicknesswise outward without striking any obstruction.

The separators 180, 181 and 182 are all drawn outwardly the maximum distance and there is an appreciable space provided between the platen 15 and the ribbon 166 along an appreciable length of the platen 15.

At this stage the pack of sheets is in the normal manner fed to a front strike typewriter by feeding the same to the rear of the platen and between the platen and the deflector plate 43.

When the pack of ribbons is in operative position the lower edge thereof is located just slightly above the forward edge of the deflector plate. When the individual ribbons of the pack are in extended position for paper interleaving purposes and as the leading edge of sheet 1 is fed forwardly it feeds by the forward edge of the deflector plate, then the leading corner of sheet 1 strikes the innermost ribbon 166 to be guided between the inner face of ribbon 166 and the platen. At this point the inner ply of ribbon 166 is actuated inwardly by separator 182. This tensioned ribbon snaps into position and forces the leading edge of the work sheet 1 snugly against the platen. Because of the oblique disposition of the ribbon, the leading edge of sheet 1 slides or slithers by the lower edge of the taut ribbon 166 and the leading corner of sheet 2 as it leaves the forward edge of the deflector 43. 35 It is automatically guided by the deflector to feed between the ribbons 166 and 167. The leading corner of sheet 2 strikes the inner surface of ribbon 167. The tensioned ribbon 167 is actuated inwardly by its separator 181 and said ribbon 167 will snap into position to force the leading edge of sheet 2 snugly between ribbons 166 and 167. Then as the work sheets are fed still further forward, sheet 1 slides between the platen and ribbon 166 and sheet 2 slides between ribbons 166 and 167 both of which are constantly 40 under tension. During continued feeding of the work sheets, the leading corner of sheet 3, like the leading corners of sheets 1 and 2, feeds by the deflector 43 and is maintained at such an angle that it strikes the inner face of ribbon 168, then ribbon 168 is snapped into position to force sheet 3 against ribbon 167, and upon still further feeding of the work sheets, sheet 4 will automatically position itself outside of ribbon 168. 45

All the ribbons are now properly interleaved with the work sheets for manifolding purposes. The work sheets may now be squared in a single uniform pack and the lever 16 swung back to actuate the front and rear rolls to force the 60 sheets against the platen and maintain them in position. The paper bail is then brought against the work sheets in the normal manner.

It will be seen that when any ribbon is adjacent the platen and under tension a work sheet 65 will automatically feed around and outside that ribbon, but when any separator with its ribbon is extended the ribbon will act as a deflector to guide the leading edge of the work sheet inside that ribbon, between it and the platen. It will be understood that the paper deflecting plate 40 which surrounds the lower portion of the platen aids in sliding the work sheet into proper position so that a work sheet can not normally feed outside of any extended ribbon, even though the 70 75

work sheet naturally tends to flare out from the platen to an extent as it emerges around the under side of the platen. It will be seen also that the oblique disposition of the ribbon provides one low end of the effective stretch which is particularly efficient in guiding the leading edge of the work sheet in a smooth and effective manner.

It is not necessary to feed the work sheets in a pack, but optionally each sheet may be fed individually, but in any case the separators are actuated to position each fed work sheet with desired relation to the ribbons.

A desired operating angle of the effective stretch is selected to match the length of lines to be typed.

The sliding element 215 is slid very close to its pivot point along arm 205 of the lower lever to provide only a very slight feeding of the strips upon each full actuation of this lever. Since the feed of ribbon per line of writing may now be, perhaps only $\frac{1}{8}$ ", only a very few inches of ribbon will be ejected from the machine for each normal full sheet of typing that is written, so that a supply spool of even several plies will last a rather long time, as it may include 200 feet or more of ribbon.

Since the feed per line is very slight, each succeeding line of impacts will strike upon almost the same carbon surface as the last preceding line of impacts, but the ribbon gradually moves into new surface both lengthwise and widthwise, and all reasonable portions of the ribbons which have been fed past the platen will have been satisfactorily exhausted of pigment. Alternately, a greater degree of ribbon feed may be allowed to occur upon each actuation of the lever, and the lever actuated only occasionally, although the slow constant uniform rate of feed is desirable for uniform work.

The typist may of course type upon continuous work sheets or forms, from rolls or packs, which forms are merely written upon and each set of forms torn off as completed. The oblique disposition of the ribbons prevents the perforations of the continuous forms from striking the ribbons as bluntly as would otherwise be the case, and the ribbons are therefore much less susceptible to breakage or tangling with the perforations.

In all types of work I use a ribbon whose width is equal to more than twice, and preferably about four to six times the height of a normal capital letter character. The inclination of the oblique stretch between the ends of the platen is preferably as great as possible and should be greater than one half the width of the ribbon to derive the greatest benefit from the use of the oblique feed.

Although I have described in detail a machine embodying my invention, it is to be understood that many modifications may be made without departing from the spirit or scope of the invention and I am therefore not to be limited to the construction shown and described except as defined in the claims.

Common or like subject matter of invention disclosed in this application and in my applications Serial No. 76,621 filed April 27, 1936, Serial No. 80,753 filed May 20, 1936, and Serial No. 93,323 filed July 30, 1936, is claimed in this application.

What is claimed:

1. A front-strike typewriting machine including a traveling platen carriage, a rotary cylindrical platen journaled in said carriage, a horizontal

shaft extending outward from one end of said platen longitudinally of the platen and connected with the platen for rotating the latter, a spool of ink-transfer ribbon journaled on the carriage adjacent the opposite end of the platen, ribbon guides on the carriage adjacent each end of the platen for guiding a stretch of ribbon from said spool diagonally downward in front of the platen from said opposite end of the platen to said first-mentioned end of the platen, a pair of upstanding ribbon-gripping feed rolls for feeding ribbon from said spool through said guides and ejecting said ribbon from the machine, said rolls being mounted on the carriage forward of said shaft, and means mounted on the carriage for directing ribbon ejected by said rolls toward the rear of the carriage and under said shaft.

2. In a writing machine, a tensioning device for a spooled ink-transfer ribbon including a ribbon spool, a toothed gear mounted for rotation by the ribbon spool and to rotate the spool, a mutilated toothed gear rotatably mounted to mesh with the first-mentioned gear, and means connected with the second-mentioned gear to yieldingly rotatively urge the latter in a direction to drive the first-mentioned gear to drive the spool to wind ribbon on said spool.

3. In a writing machine, a tensioning device for a spooled ink-transfer ribbon comprising, in combination, a ribbon spool, a toothed gear mounted for rotation thereof by the spool and to rotate the spool, an oscillatable mutilated toothed gear rotatably mounted to drive, and to be driven by, the first-mentioned gear during a part only of one revolution of said mutilated gear about its axis, resilient means connected to said mutilated gear to yieldingly drive the latter in a direction to drive the first-mentioned gear to drive the spool to wind ribbon on the spool, and means to positively limit the extent to which said resilient means can drive said mutilated gear about its axis.

4. In a writing machine, a tensioning device for a spooled ink-transfer ribbon comprising, in combination, a ribbon spool, a toothed gear mounted for rotation thereof by the spool and to rotate the spool, an oscillatable mutilated toothed gear rotatably mounted to drive, and to be driven by, the first-mentioned gear during a part only of one revolution of said mutilated gear about its axis, resilient means connected to said mutilated gear to yieldingly drive the latter in a direction to drive the first-mentioned gear to drive the spool to wind ribbon on the spool, means to positively limit the extent to which said resilient means can drive said mutilated gear about its axis, and means for manually adjusting the force of said resilient means.

5. In a writing machine having a traveling platen carriage, a ribbon spool mounted on the carriage adjacent one end of the carriage, a pair of ribbon-gripping feed rolls mounted on the carriage adjacent the opposite end of the carriage to draw ribbon from said spool, a hand lever pivoted on the carriage adjacent the last-mentioned end of the carriage, means for limiting the extent of pivotal throw of said lever, a drum on the carriage having a one-way driving connection with one of said feed rolls, and a cable wound on and anchored at one end to said drum and anchored at its other end to said lever for driving of said feed rolls to draw a ribbon from said spool when said lever is swung in one direction.

6. In a writing machine having a traveling

75

5 platen carriage, a ribbon spool mounted on the carriage adjacent one end of the carriage, a pair of ribbon-gripping feed rolls mounted on the carriage adjacent the opposite end of the carriage to draw ribbon from said spool, a hand lever pivoted on the carriage adjacent the last-mentioned end of the carriage, means for limiting the extent of pivotal throw of said lever, a drum on the carriage having a one-way driving 10 connection with one of said feed rolls, a cable wound on and anchored at one end to said drum and anchored at its other end to said lever for driving of said feed rolls to draw a ribbon from said spool when said lever is swung in one direction, and means for anchoring said cable to said lever at different selected distances from the pivotal axis of the lever to vary the length of ribbon fed by said rolls.

6 7. A writing machine, including a carriage, a 20 ribbon movable with said carriage, a supply therefor, said ribbon extending from said supply and in operative position located in the normal writing line of said machine, said so located ribbon being disposed at an oblique angle to said line, ribbon gripping means for feeding said ribbon, and means for limiting the movement of said gripping means to feed said ribbon in uniform steps along said path in each feeding operation of said ribbon.

8 8. A manifolding front-strike typewriter, including a carriage, a ribbon movable with said carriage, a supply therefor, said ribbon extending from said supply and in operative position located in the normal writing line of said machine, said so located ribbon being disposed at an oblique angle to said line, ribbon-gripping means for feeding said ribbon, means for limiting the movement of said gripping means to feed said ribbon in uniform steps along said path in each feeding operation of said ribbon, and means for variably limiting the degree of feed.

9 9. A writing machine, including a carriage, a ribbon movable with said carriage, a supply therefor, said ribbon extending from said supply and in operative position located in the normal writing line of said machine, said so located ribbon being disposed at an oblique angle to said line, ribbon-gripping means for feeding said ribbon a sufficient amount to provide a completely 35 fresh transfer surface upon each single actuation of said gripping means, and means for limiting the movement of said gripping means to feed said ribbon in substantially uniform steps along said path in each feeding operation of said ribbon.

10 10. A manifolding front-strike typewriter, including a movable letter space carriage, a platen, a supplementary carriage-carried ribbon, a supply spool for said ribbon, said ribbon extending from said supply spool with an effective stretch thereof located along the platen in the writing line and disposed obliquely thereto, ribbon-gripping rolls for engaging the free end of the ribbon to feed it therethrough, means limiting the 45 movement of said gripping rolls to feed said ribbon in uniform steps, ribbon-tensioning means to maintain the ribbon taut and in accurate oblique register with the writing line, a movable member on said carriage for engagement to move 50 said carriage to initial writing position, and means operatively connecting said member to said ribbon-gripping rolls to rotate said rolls upon movement of said carriage.

11 11. A front-strike typewriter, including a carriage, a platen, a carriage carried ribbon, a sup-

ply therefor, said ribbon extending from said supply and disposed at an oblique angle to the normal writing line of said machine, an effective stretch of said so disposed ribbon operatively located in said line whereby the extremities of a full line of writing impact close to both the upper and lower edges of said ribbon, the width of the ribbon being greater than twice the height of any normal type character of said typewriter whereby a plurality of separate lines of writing 10 may be impacted across the width of said ribbon, said stretch being adapted to have a face thereof in contact with a work sheet during the entire course of typing a plurality of characters therewith, said stretch having a high end and a low 15 end, and means for feeding said ribbon from said supply, toward said high end, thence toward said low end, and thence toward said feeding means.

12 12. A writing machine including a carriage, a 20 line spacing mechanism adjacent one end of the carriage, a supplementary ribbon carried by and movable with said carriage, a supply therefor, a stretch of said ribbon extending from said supply and in operative position located in the normal writing line of said machine, said so located stretch of ribbon being disposed at an oblique angle to said line, ribbon-gripping means for ejecting the free end of said ribbon and for uniformly feeding said ribbon from said supply 30 and along said oblique path, whereby the force of feeding of said ribbon by said gripping means is such that its component parallel to the force of feeding of a work sheet during line-space movement thereof is in a direction opposite to said direction of feeding of said work sheet, retractive means for tensioning said ribbon, said retractive means located at the other end of said carriage, and a lever carried by said carriage and operatively connected to said gripping means 35 whereby upon a single actuation of said lever said gripping means is actuated to move said supplementary ribbon a sufficient amount in the direction of its length to provide a substantially complete fresh surface of impression transfer material for a next succeeding line of writing, said lever and said gripping means being located at the end of the carriage adjacent the line-space mechanism.

13 13. A front-strike typewriter, including a letter-space carriage, a platen, a supplementary ribbon movable with said carriage and carried by said carriage, a supply therefor, said supply carried by said carriage, a stretch of said ribbon extending from said supply and in operative position located in the normal writing line of said machine, said so located stretch of ribbon being disposed at an oblique angle to said line, a pair of ribbon-gripping rolls for uniformly feeding said ribbon from said supply and along said oblique path, said rolls carried by said carriage, a portion of said stretch of ribbon being higher than another portion thereof, a carriage control member operatively connected to said feed rolls whereby upon a single actuation of said member said feed rolls are actuated to move said ribbon in said oblique path a sufficient amount to provide a substantially complete fresh surface of impression transfer material for a next succeeding line of writing, and means for limiting the 50 degree of movement of said ribbon whereby said movement is substantially uniform for each actuation of said member.

14 14. A writing machine including a carriage, a supplementary ribbon movable with and carried

- by said carriage, a supply therefor, a stretch of said ribbon extending from said supply and in operative position located in the normal writing line of said machine, said so located stretch of 5 ribbon being disposed at an oblique angle to said line whereby the impacts at the extremities of a full line of writing are close to the upper and the lower edges of said ribbon, the width of said ribbon being greater than twice the height of any 10 normal type character of said machine and whereby a plurality of separate lines of writing may be impacted on the ribbon, ribbon-grip feeding means for uniformly feeding said ribbon from said supply and along said oblique path, means 15 for tensioning said ribbon, a lever carried by said carriage and operatively connected to said feeding means whereby upon a single actuation of said lever said feeding means is actuated to move said supplementary ribbon in the direction of its 20 length to provide a substantially complete fresh surface of impression transfer material for a next succeeding line of writing, and means for reducing the amount of feed of said ribbon by a single actuation of said lever.
15. A manifolding writing machine, including a platen, a movable carriage, a plurality of strips of impression transfer material carried by said carriage, supply means therefor, said strips extending from said supply, and being disposed at 25 an oblique angle to the normal writing line of said machine, an effective stretch of said so disposed strips being operatively located in said line, the strips of said stretch being adapted to have work sheets interleaved therewith, means for 30 tensioning said strips, a pair of grip feeding rolls for simultaneously feeding said strips from said supply and ejecting the free ends thereof, and means for limiting the degree of feed.
16. A manifolding front-strike typewriter, including a movable carriage, a platen, a plurality of strips of impression transfer material carried by said carriage, supply means therefor, said strips extending from said supply and being disposed at 35 an oblique angle to the normal writing line of said typewriter, an effective stretch of said so disposed strips being operatively located in said line, the strips of said stretch being adapted to have work sheets interleaved therewith, strip-grip feeding means for engaging the free ends of 40 said strips and feeding them therethrough, retractive tensioning means imparting a force to said strips tending to pull said strips toward said supply and away from said grip feeding means, and means for limiting the degree of feed.
55. 17. A writing machine including a movable reciprocating carriage, a plurality of strips of impression transfer material carried by said carriage, a multiple-ply supply spool therefor, said strips extending from said supply and being disposed at 45 an oblique angle to the normal writing line of said machine, an effective stretch of said strips being operatively located in said line, the strips of said stretch being adapted to have work sheets interleaved therewith, a grip feeding 50 means for engaging the free ends of said strips and ejecting the same out of said means, strip-retraction means tending to rotate said spool in a direction opposite to its direction of rotation during feeding of the strips therefrom, to maintain the strips under tension, and means for 55 limiting the degree of feed.
18. A front-strike manifolding typewriter, including a carriage, a platen, a plurality of strips of impression transfer material supported by said carriage, a supply therefor, said strips ex-

tending from said supply and being disposed at an oblique angle to the writing line of said machine, an effective stretch of said strips being operatively located in said line, one end of the effective stretch being higher than its other end, 5 means for tensioning said strips, and strip-gripping means for feeding said strips along said path from said supply and toward said higher end, and then toward said low end and then toward said grip feed means and through and out of said 10 grip feed means, said strips thereby being fed obliquely downward relative to the normal upward line spacing of work sheets interleaved with said strips.

19. A typewriter including a carriage, an impression transfer ribbon extending along said carriage, a supply therefor, said ribbon extending from said supply, a portion of said ribbon being located in the normal writing line of said typewriter, said portion supported by and movable 20 with said carriage, means for feeding said ribbon from said supply in the direction of its length and along said normal writing line, and means for moving a part of said portion through a longer arcuate path than another part thereof to 25 vary the angular relationship between said ribbon and said line.

20. A typewriter including an impression transfer ribbon, a supply therefor, said ribbon extending from said supply and being located in 30 the normal writing line of said typewriter, means for feeding said ribbon substantially uniformly in the direction of its length, means for regulating the amount of feed, and means for varying the angular relationship between said ribbon and 35 said line.

21. A typewriter including an impression transfer ribbon disposed at an oblique angle to the normal writing line of said typewriter, a supply therefor, said so disposed ribbon being 40 located in said line, means for varying the angular relationship between said ribbon and said line, and means for feeding said ribbon from said supply.

22. A typewriter including an impression transfer ribbon, a supply therefor, said ribbon extending from said supply and located in the normal writing line of said typewriter, said so located ribbon being disposed at an oblique angle to said line, means for feeding said ribbon substantially uniformly from said supply, means for regulating the amount of feed, and means for varying the angular relationship between said ribbon and said line.

23. A typewriter including an impression transfer ribbon disposed at an oblique angle to the normal writing line of said typewriter, a supply therefor, said so disposed ribbon being located in said line with a portion of said ribbon being higher than another portion thereof, means 60 for feeding said ribbon from said supply, and means for lowering and raising the higher portion of said ribbon with respect to its other portion to vary the angular relationship between said ribbon and said line and locate said ribbon in selective portions of said line.

24. A writing machine, including a strip of impression transfer material, a supply therefor and a feeding means for said strip, said strip being disposed at an oblique angle to the normal writing 70 line of said machine, an effective stretch of said so disposed strip being operatively located in said line, and means for varying the angular relationship between said strip and said line to move part of said effective stretch out of said line to vary 75

the length of said effective stretch operatively located in said line.

25. A writing machine, including a strip of impression transfer material, a supply therefor, said strip extending from said supply and in register with the normal writing line of said machine, an effective stretch of said so located strip being operatively disposed at an oblique angle to said line, a strip guide adjacent one end of the effective oblique stretch for varying the operative angular relationship between said strip and said line, means for maintaining said guide in a plurality of different positions to maintain said stretch in registry with selective portions of said line, means for substantially uniformly feeding said strip, and means for varying the degree of feed.

26. A writing machine including a movable carriage, a strip of impression transfer material, a supply therefor, said strip extending from said supply and in register with the normal writing line of said machine, an effective stretch of said so located strip being operatively disposed at an oblique angle to said line, strip guiding means for varying the operative angular relation between said strip and said line, means for maintaining said guide means in a plurality of positions to maintain said stretch in operative registry with the entire maximum writing line or only a portion thereof, strip gripping means for feeding said strip along the said oblique path of said stretch and out of said means, a manually operable lever supported by said carriage and operably connected to said feeding means, and means to control the degree of feed of said strip by said gripping means for each full actuation of the lever.

27. A front-strike typewriter, including a platen, a movable carriage, a ribbon guide adjacent an end of the carriage adjacent the point of normal beginning of a line of writing, an adjustable ribbon guide, located adjacent the other end of the carriage and vertically higher than said first-mentioned guide, a supplementary carriage ribbon, a supply therefor, ribbon feeding means adjacent the said first-mentioned ribbon guide, said ribbon extending from said supply to said high guide, then obliquely downward along said platen to said first guide and thence to said feeding means, an effective stretch of said obliquely disposed ribbon being operatively in register with the writing line, and means to maintain said adjustable guide in a plurality of positions whereby said stretch may be in register with selective portions of the maximum writing line and may be operatively disposed at different oblique angles to said line.

28. A writing machine including a frame, a carriage, supporting means for a supply of impression transfer material, said supporting means being adapted to be moved with respect to both said frame and carriage to vary the location thereof with respect to said frame and carriage, and feeding means for said impression transfer material, the location of said feeding means with respect to said carriage being substantially unaffected during movement of said supporting means with respect to said frame and carriage, both of said means being carried by said carriage.

29. A writing machine including a frame, a carriage, supporting means for a supply of impression transfer material, said supporting means connected to and movable with said carriage, feeding means for feeding said impression trans-

fer material from said supply, said feeding means connected to and movable with said carriage, said supporting means adapted to be moved with respect to both said frame and carriage to vary the location of said supporting means with respect to said frame and carriage, the location of said feeding means with respect to said carriage being independent of the location of said supporting means during movement thereof with respect to said frame and carriage, and means for maintaining said supporting means in a plurality of locations with respect to said frame and carriage.

30. A typewriter including a frame, a carriage, a supply of impression transfer ribbon carried by said carriage and adjacent one end of said carriage, a stretch of said ribbon extending from said supply and disposed at an oblique angle to the normal writing line of said typewriter, the so disposed stretch being located in said line, means for feeding said ribbon from said supply along the path of said oblique stretch and toward said feed means, and means for moving said supply in unison with one end of said stretch to vary the angular relation between said stretch and said line.

31. In a front-strike typewriter including a frame and a letter-space movable carriage, the combination of a carriage ribbon, a supply spool therefor, said spool movable with said carriage upon letter-space movement thereof and located near one end of said carriage, grip feed means movable with said carriage upon letter-space movement thereof and located near the other end of said carriage, an effective stretch of said ribbon extending from said supply and in operative position being disposed at an oblique angle to and in register with the normal writing line of said typewriter, guide means for maintaining said stretch in said position, one portion of said stretch being located adjacent said supply spool, said portion being higher than that portion of said stretch located adjacent said feed means, and means for moving in unison the high portion of said stretch with respect to said other portion thereof, and said spool with respect to said feed means to vary the angle which said stretch makes with said line.

32. In a front-strike typewriter including a frame, a carriage and a platen, the combination of a carriage carried ribbon, a supply therefor, an effective stretch of said ribbon being disposed at an oblique angle to and in operative register with the normal writing line of said typewriter, grip feed means for feeding said ribbon along said path, a movable ribbon guide adjacent one end of said platen, and a resilient means for urging said guide toward one limit of its travel, said guide adapted to be moved toward the other limit of its travel and against the action of said resilient means, the angular relationship of said ribbon with said line being varied when the position of said guide is changed.

33. In a front-strike typewriter including a frame, a carriage and a platen, the combination of a strip of impression transfer material, a supply therefor, said strip extending from said supply and along said platen, an effective stretch of said strip being disposed at an oblique angle to and in register with the normal writing line of said typewriter, grip feeding means for feeding said strip from said supply and along said path, a movable guide for said strip, an adjustable stop for limiting the position of said guide at one of its limits of travel, and a resilient means urging

said guide to said limit of travel determined by said stop.

34. In a front-strike typewriter including a frame and a carriage, the combination of a carriage carried ribbon, a supply therefor, said ribbon extending from said supply, an effective stretch thereof in operative position in effective register with the writing line of said typewriter, grip feed means for feeding said ribbon from said supply, a guide for said ribbon, resilient means for maintaining said guide in one location with respect to said feed means, said guide adapted to be moved to another location with respect to said feed means and against the action of said resilient means to move said stretch with respect to said line, and means for locking said guide in said second location.

35. The combination with a typewriter including a frame, a movable carriage, a platen carried by said carriage, and a ribbon vibrator, of a carbon ribbon, a supply therefor carried by said carriage and movable with said carriage, said carbon ribbon extending from said supply and along said platen and disposed at an oblique angle to the normal writing line of said typewriter, said so disposed carbon ribbon being located in said line, gripping means for feeding said ribbon from said supply, said gripping means carried by said carriage, means for varying the angular relation between said carbon ribbon and said line to move said so disposed carbon ribbon to inoperative position where the upper edge of said carbon ribbon is located below said writing line and between said platen and said vibrator, means for maintaining said ribbon in said inoperative position, and means for relocating said ribbon in its original operative position.

36. A writing machine including a ribbon of impression transfer material, a supply therefor, said ribbon extending from said supply, and in operative position located in the normal writing line of said machine, said so located ribbon being disposed at an oblique angle to said line, means for maintaining said ribbon substantially stationary in the direction of its width during the entire course of writing a plurality of impressions therewith, means for moving a portion of said obliquely disposed ribbon through a longer arcuate path than another portion thereof in a direction tending to make said ribbon parallel to the writing line to locate said ribbon entirely to one side of said writing line in inoperative position, and means for maintaining said ribbon in said inoperative position.

37. A writing machine including a strip of impression transfer material, a supply therefor, said strip extending from said supply, and in operative position located in the normal writing line of said machine, said so located strip being disposed at an oblique angle to said line, means for feeding said strip from said supply, a portion of said so disposed strip being higher than another portion thereof, and means for lowering the higher portion of said strip with respect to its other portion to locate said strip entirely below said writing line in inoperative position.

38. A front-strike typewriter, including a carriage and a rotatable platen, a strip of impression transfer material supported by said carriage and movable therewith, a supply therefor, said strip extending from said supply and in operative position located in the normal writing line of said typewriter, said so located strip being disposed at an oblique angle to said line, strip-gripping means for feeding said strip uniformly, a portion

of said so disposed strip being higher than another portion thereof, means for lowering the higher portion of said strip with respect to its other portion to locate said strip entirely below said writing line in inoperative position, means for maintaining said strip in inoperative position, and retractive tension means to maintain the strip taut in operative and inoperative positions, the location of said strip feeding means with respect to said carriage being substantially fixed during movement of the strip from operative to inoperative position.

39. A writing machine, including a movable carriage, a strip of impression transfer material, a supply therefor, said strip extending from said supply and in operative position located in the normal writing line of said writing machine, said so located strip being disposed at an oblique angle to said line, a portion of said so disposed strip being lower than another portion thereof, strip-gripping means for feeding said strip from said supply and along said path, said means supported by said carriage and located adjacent one end of the carriage and adjacent the said lower portion of said strip, and means adjacent the opposite end of the carriage and adjacent the higher portion of the strip, said last means adapted to lower the higher portion of the strip with respect to the lower portion to locate said strip entirely below said line in inoperative position, the location of said feed means with respect to said carriage being substantially fixed in the course of rendering said strip inoperative, the path of strip feeding when the strip is in operative position being obliquely downward along the writing line and toward said grip feeding means.

40. A writing machine including a movable carriage, a platen, line-space mechanism adjacent one end of the carriage for rotating said platen, a carriage return lever adjacent said end of the carriage, a strip of impression transfer material, a supply therefor, a stretch of said strip extending from said supply and in operative position located in the normal writing line of said machine, said so located stretch being disposed at an oblique angle to said line, said stretch having a high portion and a low portion with the high portion located adjacent the opposite end of said carriage, strip-grip feeding rolls for feeding said strip along the oblique path of said stretch and from its high end toward its low end, said rolls supported by said carriage and located near the end thereof adjacent said lever, means operatively connecting said lever to said rolls whereby upon actuation of said lever said rolls are rotated to feed said strip, and means for lowering the high portion of said strip with respect to the low portion thereof and the feed means to lower the strip to inoperative position, with the upper edge of said strip disposed below the writing line.

41. In a front-strike typewriter including a frame and carriage, the combination of a strip of impression transfer material, a supply spool therefor, said strip extending from said supply and an effective stretch thereof in operative position being disposed at an oblique angle to and in register with the normal writing line of said typewriter, said spool supported by said carriage near one end thereof, and grip feeding means for feeding said strip from said spool, said supply spool being adapted to be moved independently of said feed means and in unison with one end of said stretch to move said stretch downward and substantially entirely out of register with

said line, said feed means being supported by said carriage near the other end thereof adjacent the low end of said stretch, the path of feeding of said strip being from the supply spool 5 and obliquely downward toward said feed means and to and through said feed means.

42. A front-strike writing machine including a platen, a strip of impression transfer material, a supply therefor, said strip extending from said 10 supply and along the front of said platen, said strip being disposed in the direction of its length obliquely to the normal writing line of said machine with the strip facing the platen, an effective stretch of said strip being located in said line, 15 and means adjacent the lower end of said obliquely disposed strip for moving said so disposed strip from the platen to sheet-guiding position, said strip in sheet-guiding position being adapted to guide the leading edge of a work sheet 20 between the platen and said strip in the course of mounting said sheet in said machine.

43. A writing machine including a carriage, a platen, a carriage carried ribbon, a supply therefor, means for guiding a work sheet upwardly as it is fed around said platen, said ribbon extending along said platen and disposed at 25 an oblique angle to the normal writing line of said machine, an effective stretch of said ribbon being located in said line and closely adjacent 30 said platen, whereby a work sheet fed around the platen will normally feed outside of said ribbon, said so disposed stretch of ribbon having a low end, separating means located at the low end of said stretch for separating said low end from 35 said platen, whereby a work sheet fed around the platen will have its leading edge guided between said stretch of ribbon and said platen, and means for tensioning said ribbon in both said positions.

44. A front-strike manifolding typewriter including a carriage, a rotatable platen, a plurality 40 of strips of impression transfer material supported by said carriage and movable therewith, a supply therefor, said strips extending from said supply and disposed at an oblique angle to the normal writing line of said typewriter, the effective stretch of said so disposed strips being located in said line and closely adjacent said 45 platen, a plurality of independently operable means for moving said strips from said platen and with respect to each other, all of said means being located at the lower end of said strips, and means for maintaining said strips under tension. 50

45. A writing machine including a carriage, a carriage carried ribbon, a supply therefor, 55 a platen, a deflector adjacent said platen for deflecting a work sheet around the platen and upwardly, a stretch of said ribbon extending along said platen, said stretch extending from said supply and disposed at an oblique angle to the normal writing line of said machine, an effective 60 portion of said so disposed ribbon being located in said line and closely adjacent the platen, whereby a work sheet fed around the platen will normally feed outside of said ribbon, said stretch having a low end, ribbon-grip feeding means for 65 feeding said ribbon along said path and from said supply, and separating means located adjacent the low end of said stretch for separating the low end of said stretch from said platen whereby 70 a work sheet fed around the platen will have its leading edge guided between said ribbon and said platen, said separating means being located adjacent said feeding means.

46. A manifolding writing machine including a 75 reciprocating carriage, a platen carried thereby,

a plurality of superposed individual strips of impression transfer material movable with said carriage, an effective stretch of said superposed strips in operative position being located in the normal writing line of said machine, supply 5 means for said strips, grip feed means for simultaneously moving lengthwise the strips of said stretch, said stretch including an inner strip and an outer strip, a plurality of separators for moving a portion of both of said strips of said stretch 10 away from said platen and operative position to such an extended position that a work sheet fed around said platen is guided between said inner strip and said platen by said inner strip, said separators carried by said carriage and being independently actuatable to return said strips one by one to their operative positions whereby the extended inner strip may be returned to its operative position upon actuation of one of said separators and the other strip may be maintained in its extended position so that a second work sheet fed around said platen will be guided 15 between said outer and inner strips by said outer strip, said outer strip being adapted to be returned to its operative position by actuation of another of said separators while said inner strip 20 is in operative position, and means for maintaining taut the strips of said stretch when in operative position, when in extended position, and when one of said strips of said stretch is in 25 operative position and another strip of said stretch is in extended position.

47. A manifolding writing machine comprising a reciprocating carriage, a platen carried thereby, a plurality of superposed strips of impression 30 transfer material, supply means therefor, said strips extending from said supply means and in operative position an effective stretch of said superposed strips being in register with the normal writing line of said machine, a common 35 guide for a plurality of said strips, said guide located adjacent one end of said platen for guiding said strips widthwise in their operative path, a pair of strip-grip rolls for feeding said strips and ejecting the free ends thereof, said rolls located adjacent one end of said platen, a plurality 40 of separators for separating a portion of the effective stretch of said strips from said platen, said separators being independently actuatable to return the strips of said stretch to their original positions whereby the strips may be returned one by one to their original positions, said separators located adjacent the platen near the feed means, and tensioning means for maintaining all of said strips taut at substantially all 45 times and located adjacent that end of the platen remote from said feed means.

48. A manifolding front-strike typewriter including a movable carriage, a platen, a plurality 50 of carriage-carried individual strips of impression transfer material, a supply therefor, said strips extending from said supply and along said platen, common strip-grip feeding means for feeding said strips in unison, means adjacent one end of said platen for separating said strips thicknesswise, and slack take-up means for tensioning said strips when they are in operative position during 55 typing, and for tensioning one of said strips when it is close to the platen and another of said strips spaced from said first strip and away from said 60 platen during paper-interleaving.

49. A front-strike manifolding typewriter including a carriage, a platen, a plurality of strips of impression transfer material, a supply therefor, said strips extending from said supply and along 70

- said platen, and in operative position an effective stretch thereof being in register with the normal writing line of said machine and operatively disposed at an oblique angle thereto, a plurality of 5 individually operable strip separators adjacent one end of said carriage for moving said strips with respect to each other for paper interleaving, and means located near the other end of said carriage for varying the angular relationship between 10 said strips and said line to lower said strips below said line in inoperative position whereby the upper edges of said strips are below said line.
50. A manifolding front-strike typewriter including a movable carriage, a platen, a supply 15 of impression transfer strips supported by said carriage and located near the right-hand end thereof, said strips extending from said supply and along said platen and in operative position an effective stretch thereof being disposed at an 20 oblique angle to and in register with the normal writing line of said typewriter, a strip guide adjacent the left-hand end of said carriage, said stretch extending obliquely downward toward the left-hand end of said carriage, strip-gripping 25 means adjacent the left-hand end of said carriage for feeding said strips, means adjacent the right-hand end of said carriage for varying the angular relationship between said strips and said line, means for tensioning said strips, and a plurality 30 of individually operable strip separators adjacent the left-hand end of said carriage for separating said strips from each other for paper interleaving.
51. A writing machine including an impression 35 transfer ribbon, a supply therefor, means for feeding said ribbon from said supply, and retractive tensioning means including two elements adapted to be in positive mesh, one of said elements rotatably driven by ribbon-feeding operation, resilient means, the other element movable 40 against the action of said resilient means and driven to a predetermined position by rotation of said first element whereby said elements slip with respect to each other and against the action 45 of said resilient means during continued rotation of said first element, said resilient means being adapted to force said second element into positive mesh with said first element to counter-rotate said first element and to take up slack in the 50 ribbon.
52. A writing machine including an impression transfer ribbon, a supply therefor, means for feeding said ribbon from said supply, and retractive ribbon-tensioning means including two 55 elements adapted to be in positive mesh, one of said elements rotatably driven by ribbon-feeding operation, a spring, the other element movable against the action of said spring and driven to a predetermined position by rotation of said first 60 element whereby said elements slip with respect to each other and against the action of said spring during continued rotation of said element, said spring means being adapted to force said second element into positive mesh with said 65 first element to counter-rotate said first element to take up slack in the ribbon, said spring being manually adjustable to vary the degree of counter-rotative force imparted to said first element.
53. A writing machine including an impression 70 transfer ribbon, a supply spool therefor, means for feeding said ribbon from said spool, a toothed disc rotatable with the spool upon feeding of said ribbon from said spool, means adapted to engage positively with said teeth, and a spring, 75 said second means being adapted to be moved

against the action of said spring and by said disc to one position, the degree of movement of said second means to said position being independent of long-continued rotation of said disc in one direction whereby said elements slip with respect to each other and against the action of said spring means.

54. A typewriter including a movable carriage, a carriage-carried impression transfer ribbon, a supply spool therefor, means for feeding said 10 ribbon from said spool, a toothed disc rotatable with the spool upon feeding of ribbon from said spool, means adapted to engage positively with said teeth, a spring, said second means adapted to be moved against the action of said spring 15 and by said disc to one position, the degree of movement of said second means to said position being independent of long-continued rotation of said disc in one direction whereby said elements slip with respect to each other and against the 20 action of said spring, said second means being adapted to counter-rotate said spool by the action of said spring, and means independent of said spring for limiting the counter-rotation of said disc.

55. A manifolding typewriter including a plurality of strips of impression transfer material, a supply therefor, said strips extending effectively along a writing line, a common feed means for feeding the pack of strips and including a 30 pair of pressure rolls, each of said rolls having a gripping surface, and a gear independent of said surfaces fixed to each roll, said gears located beyond the active portion of said gripping surfaces and being independent of said gripping surfaces, whereby said rolls are positively rotated in unison and a driving force is imparted to one of said strips by the gripping surface of one of said rolls, and a driving force is imparted to another of said strips by the gripping surface of 40 the other of said rolls upon actuation of said rolls.

56. A writing machine including a reciprocating carriage, a carriage-return lever carried by said carriage, a pair of ribbon-feed rolls carried 45 by said carriage, both said lever and said rolls located near the same end of said carriage, said rolls located beyond said lever, means connecting said rolls to said lever whereby upon actuation of said connecting means by said lever said 50 rolls are rotated, and means for varying the point of connection between said means and said lever to vary the degree of rotation of said rolls.

57. The combination with a writing machine of the kind wherein types and a platen are 55 mounted for coaction along a straight writing line extending longitudinally of the platen, and wherein said platen presents along said line a convex surface curved transversely of said line, of a supply of impression-transfer ribbon, a 60 length of said ribbon extending from said supply and along said platen, an effective stretch of said length being operatively disposed at an oblique angle to and being in register with said writing line of said machine, means for causing 65 the path of said stretch independent of work-piece pressure to be substantially helical, and means for feeding said ribbon from said supply and along said path.

58. The combination with a writing machine 70 of the kind wherein types and a cylindrical platen are mounted for coaction along a straight writing line extending longitudinally of the platen, of a supply of impression-transfer ribbon, a length of said ribbon extending from said 75

supply and along said platen, means adjacent the opposite ends of said platen for guiding said length of ribbon along said platen and part-way around the platen in a helical path, an effective helical stretch of said length of ribbon being operatively in register with said writing line of said machine, and means for feeding said ribbon from said supply and along said helical path.

59. The combination with a writing machine of the kind wherein types and a platen are mounted for coaction along a straight writing line extending longitudinally of the platen, of a supply of impression transfer ribbon, a length 5 of said ribbon extending from said supply and along said platen, an effective stretch of said length being operatively disposed at an oblique angle to and being in register with said writing line of said machine, means for causing a portion 0 of the length of said stretch to extend along a helical path, means adjacent the opposite ends of said platen for guiding said ribbon, means for tensioning said ribbon, and means for feeding said ribbon from said supply along said path 5 against the action of said tensioning means.

60. The combination with a manifolding front-strike typewriter having a movable carriage, a cylindrical platen on the carriage and means for moving said carriage to provide a straight writing line extending longitudinally of the platen, of a plurality of carriage-carried ribbons, a supply therefor, said ribbons extending from said supply and along said platen, means adjacent the ends of said platen for guiding said ribbons 15 along said platen wound part-way about the platen in a helical path, an effective helical stretch of said ribbons being operatively in register with said writing line of said machine, means for simultaneously feeding said ribbons 10 from said supply and along said helical path, and slack take-up means for tensioning said ribbons to maintain the ribbons of said effective stretch compactly interleaved with work sheets and conforming snugly to the contour of the 15 platen.

61. The combination with a writing machine of the kind wherein types, and a cylindrical platen which is rotatable about its axis for line-spacing, are coactive on a straight writing line 50 parallel to the axis of the platen, of means to support a supply of ink-transfer ribbon for end-wise movement of said ribbon, means supporting an effective longitudinal stretch of such ribbon facewise to, and closely adjacent, the periphery 55 of said platen and extending in the direction of length of said stretch substantially from one end to the other of said platen and part-way around the platen in a helical path which disposes such effective stretch of ribbon at the writing line, 60 means for at will feeding said ribbon from said supply along said diagonal path and discharging the end thereof from said feeding means, and means for maintaining ribbon from such a supply under yielding tension where it is stretched 65 along the platen.

62. The combination with a front-strike typewriter having a movable carriage, a cylindrical platen on the carriage and means for moving said carriage to provide a straight writing line 70 extending longitudinally of the platen, of a carriage-carried ribbon, a supply therefor, said ribbon extending from said supply, an effective stretch thereof being operatively in register with the normal writing line of said machine and disposed at an oblique angle thereto, and a support

for said supply pivotally mounted at one end of said carriage and adapted to be swung about its pivot to vary the angular relationship between said stretch and said line.

63. The combination with a front-strike typewriter having a movable carriage, a cylindrical platen on the carriage and means for moving said carriage to provide a straight writing line extending longitudinally of the platen, of a carriage-carried ribbon, a supply therefor, said ribbon extending from said supply, an effective stretch thereof being operatively in register with the normal writing line of said machine and being disposed at an oblique angle thereto, guiding means for guiding said ribbon widthwise, means 10 for tensioning said ribbon, and a common support for said supply, guiding means and tensioning means, said support being pivotally mounted at one end of said carriage and adapted to be swung about its pivot to vary the angular relationship 15 between said stretch and said line. 20

64. The combination with a writing machine of the kind wherein a system of types and a platen are mounted for coaction on a straight writing line longitudinally of the platen, and 25 wherein said platen is convex transversely of said line, of an ink-transfer ribbon, means for guiding from a supply of said ink-transfer ribbon a longitudinal stretch of such ribbon along said platen diagonally to the writing line with such 30 stretch of ribbon disposed along the writing line with the ribbon close to and at all points transversely of the ribbon substantially equidistant from the convex surface of the platen, and means for varying the angle to the writing line at which 35 the stretch of ribbon is guided along the platen.

65. The combination with a writing machine wherein a system of types and a rotary cylindrical platen are mounted for coaction along a straight writing line parallel to the axis of the 40 platen, of an ink-transfer ribbon on the carriage, means for at will feeding endwise said ink-transfer ribbon relatively to the platen, and means for at will shifting a stretch of that ribbon substantially edgewise between an inoperative position 45 in which said stretch extends along the platen to one side of the writing line and an operative position in which said stretch winds helically part-way around the platen with ribbon in said stretch disposed facewise thereof 50 close to the platen and registering with at least a part of the length of the writing line.

66. The combination with a writing machine having a cylindrical platen, types coactive with said platen along a writing line of predetermined 55 maximum length extending parallel to the platen axis, of an ink-transfer ribbon, means for at will winding a stretch of said ink-transfer ribbon facewise of such ribbon part-way around the platen in one direction in a helical path and for 60 for at will unwinding said stretch of ribbon, said means disposing such stretch of ribbon in register with the writing line throughout at least part of the length of said line upon winding of such stretch of ribbon around the platen and disposing such stretch of ribbon to one side of said line upon unwinding of such stretch from around the platen, and means for at will feeding said ribbon from said supply along said diagonal path. 65

67. The combination with a writing machine wherein a system of types and a rotary cylindrical platen are mounted for coaction along a straight writing line which extends parallel to the axis of the platen, of an ink-transfer ribbon, 70 75

- means for at will feeding endwise said ink-transfer ribbon relatively to the platen, means for at will shifting a stretch of that ribbon substantially edgewise between an inoperative position in which said stretch extends along the platen to one side of the writing line and an operative position in which said stretch winds helically part-way around the platen with ribbon in said stretch disposed facewise thereof close to the platen and registering with at least a part of the length of the writing line, means for maintaining ribbon in said stretch under yielding tension at all times, and feeding means for at will feeding said ribbon from said supply along said diagonal path.
68. The combination with a writing machine having a cylindrical platen, types coactive with said platen along a writing line of predetermined maximum length extending parallel to the platen axis, of an ink-transfer ribbon, means for at will winding a stretch of said ink-transfer ribbon facewise of such ribbon part-way around the platen in one direction in a helical path and for at will unwinding such stretch of ribbon, said means disposing such stretch of ribbon in register with the writing line throughout at least part of the length of said line upon winding of such stretch of ribbon around the platen and disposing such stretch of ribbon to one side of said line upon unwinding of such stretch from around the platen, means for maintaining such a stretch of ribbon constantly under yielding tension longitudinally of the stretch, and means for at will feeding said ribbon along said helical path.
69. The combination with a front-strike typewriting machine of the kind having a main frame, a platen carriage mounted to travel transversely of the main frame, a rotary cylindrical platen journaled in the carriage and extending transversely of the main frame, and a ribbon and a system of types mounted on the main frame for coaction with the platen at a printing point to produce inked type impressions along a writing line which extends along and parallel to the platen axis, of a carriage-carried ink-transfer ribbon, means on the carriage adjacent one end of the carriage to feed said ink-transfer ribbon and eject it from the machine, a spool carrying said ink-transfer ribbon, means on the carriage adjacent the other end of the carriage rotatably supporting said spool of ink-transfer ribbon, ribbon-guide means on the carriage adjacent said feed means, and ribbon-guide means on the carriage adjacent said spool, said feed means and first-mentioned guide means being mounted on the carriage to anchor said stretch of ribbon at one end thereof with the upper edge of the ribbon at said end of said stretch located close to the writing line of the machine, and a mounting for the spool support and last-mentioned guide means for manual swinging thereof in unison at will on the carriage about the platen relatively to said feed means and first-mentioned guide means to wrap said stretch of ribbon helically part-way about the platen to dispose at least part of the stretch in front of the writing line and unwrap said stretch from about the platen to dispose said stretch wholly below the writing line and behind the ribbon mounted on the main frame.
70. A writing machine having a platen, an ink-transfer ribbon, means for holding said ribbon entirely to one side of the writing line of the machine adjacent one end of the platen, and means for swinging the ribbon adjacent the other

end of the platen in an arc in one direction part-way around the platen to dispose said ribbon in a helical path in register with the writing line, and for swinging the ribbon in the opposite direction to displace it entirely to one side of the writing line.

71. The combination with a front-strike typewriter having a movable carriage, a cylindrical platen on the carriage and means for moving said carriage to provide a straight writing line extending longitudinally of the platen, of a ribbon of impression-transfer material carried by said carriage and disposed at an oblique angle to the normal writing line of said typewriter, an effective stretch of said ribbon being located operatively in said line and having a high end and a low end whereby a work sheet fed around the platen will normally feed outside of said ribbon, and means for swinging the high end of the said stretch of ribbon downwardly and forwardly with respect to its low end to move said ribbon forwardly away from said platen to thereby place the downwardly shifted portion of the ribbon in position to deflect a work sheet fed around the platen between said ribbon and said platen.

72. The combination with a front-strike typewriter having a movable carriage, a cylindrical platen on the carriage and means for moving said carriage to provide a straight writing line extending longitudinally of the platen, of a ribbon of impression-transfer material carried by said carriage and disposed at an oblique angle to said writing line, an effective stretch of said so disposed ribbon operatively located in said line, one end of said stretch of said ribbon being higher than the other end thereof, a pair of spaced ribbon guides located near the ends of said writing line, said effective stretch located closely adjacent said platen, whereby a work sheet fed around the platen will normally feed outside of said ribbon, one of said guides being movable with respect to the other to swing said ribbon downwardly and forwardly and dispose said high portion of the stretch at a point below the original low portion of the stretch forwardly away from the platen to deflect a work sheet fed around the platen between said platen and ribbon by the ribbon, and means to maintain said stretch under tension.

73. The combination with a manifolding front-strike typewriter having a movable carriage, a cylindrical platen on the carriage and means for moving said carriage to provide a straight writing line extending longitudinally of the platen, of a plurality of ribbons of transfer material, a supply therefor, said ribbons extending from said supply and along said platen, an effective stretch thereof being in register with the normal writing line of said machine and being disposed at an oblique angle thereto, guide means adjacent one end of said platen for guiding said ribbons widthwise, a common guide adjacent the other end of said platen for guiding said ribbons widthwise, individually operable ribbon separators for work sheet interleaving located adjacent said common guide and therebeyond, and means for feeding said ribbons.

74. The combination with a manifolding front-strike typewriter having a movable carriage, a cylindrical platen on the carriage and means for moving said carriage to provide a straight writing line extending longitudinally of the platen, of a plurality of carriage ribbons, a supply therefor, said ribbons extending from said supply and in operative position an effective stretch thereof

being in registry with the normal writing line of said machine and operatively disposed thereto, guide means adjacent one end of said carriage for guiding said ribbons widthwise, a common 5 guide means adjacent the other end of said carriage for guiding said ribbons widthwise, individually operable means for separating said ribbons from each other for paper interleaving, and means for feeding said ribbons, said common 10 guide, said feeding and said separating means located adjacent the other end of said carriage, with said separating means located in the path of said ribbons between said common guide and said feeding means.

15 75. The combination of a front-strike writing machine having a traveling platen carriage, a rotary cylindrical platen extending longitudinally of and journaled in the carriage, of a ribbon, means on the carriage at one end of the carriage to feed and eject said ribbon, a ribbon guide on the carriage adjacent said one end of the carriage to guide a ribbon close to the front face of the platen with said ribbon below the writing line at the guide, a ribbon spool and 20 ribbon guide adjacent the opposite end of the carriage pivotally mounted on the carriage to swing up and down relatively to the carriage about an axis which is located below and behind the platen axis and extends substantially longitudinally of the platen axis, said last-mentioned ribbon guide being arranged to shift one end of a stretch of ribbon extending between said guides from said spool from an elevated position of said stretch and in which the latter is located 25 close to the face of the platen to a lowered position in which said stretch end is spaced farther from the platen than the end of such stretch guided by the first-mentioned guide, and means on the carriage between the feed means and the first-mentioned guide and shiftable forwardly at 30 will to draw the adjacent end of the ribbon stretch forward from the platen.

76. A front-strike typewriter, including a movable carriage, a carriage-carried strip of impression-transfer material, a supply therefor, said strip extending from said supply, strip-gripping means for feeding the ribbon in substantially uniform steps, and including a plurality of strip-gripping pressure rolls, a lever supported by said carriage, a flexible member operatively connecting said lever and said rolls for actuating said rolls upon actuation of said lever, and means for varying the point of connection between said

lever and said flexible member to vary the degree of feed by said rolls upon actuation of the lever.

77. A front-strike typewriter, including a movable carriage, a carriage-carried strip of impression transfer material, a supply therefor, said strip extending from said supply, strip-gripping rolls for feeding said strip from said supply, a carriage return lever supported by said carriage, a flexible driving member operatively connecting said lever and said feeding means for driving the feed rolls upon actuation of the lever, and adjustable means for varying the extent of ribbon fed by actuation of said lever.

78. A manifolding typewriter including a plurality of strips of impression-transfer material, a multiple-ply spool therefor, said strips extending effectively along the writing line of said machine, a common feed means for simultaneously feeding said strips from said spool, said feeding means including means for feeding the strip forming the outer ply a greater degree than the strip forming the inner ply fed therebetween, and means for tensioning said strips.

79. A manifolding writing machine having a platen, a ribbon supply spool, a pair of ribbon-gripping feed rolls, and a plurality of impression-transfer ribbons interwound on said spool and extending from said spool to and between said rolls with the stretch of ribbons between the spool and said pair of rolls extending along the platen and in operative register with the writing line of the machine, and means for positively driving the gripping surfaces of both of said rolls, and the gripping surface of one of said rolls at a linear speed greater than the linear speed of the surface of the other of said rolls to feed the outermost one of the ribbons from said spool a greater amount therebetween than the innermost one of said ribbons.

80. A manifolding typewriter including a plurality of strips of impression-transfer material, a multiple-ply supply spool therefor, said strips extending effectively along the writing line of said machine, and a pair of positively driven rolls for gripping the free ends of said strips and feeding them therethrough, with one strip from said spool in contact with a relatively large area of the gripping surface of one of said rolls as compared with another strip from said spool in contact with the gripping surface of the other roll, to feed one of said strips a greater amount therebetween.

WILLIAM E. McFARLAND.
